UNITED STATES PATENT OFFICE

CHARLES SULFER, OF CHICAGO, ILLINOIS, ASSIGNOR TO DIAL CASH REGISTER COMPANY, OF MILWAUKEE, WISCONSIN, A CORPORATION OF ARIZONA.

REGISTERING MECHANISM.

1,135,552.

Specification of Letters Patent. Patented Apr. 13, 1915.

Original application filed December 29, 1906. Serial No. 350,057. Divided and this application filed February 24, 1908. Serial No. 417,530.

To all whom it may concern:

Be it known that I, CHARLES SULFER, a citizen of the United States and a resident of the city of Chicago, in the county of Cook and State of Illinois, have invented 5 certain new and useful Improvements in Registering Mechanism; and I do hereby declare that the following is a full, clear, and exact description of the same, reference being had to the accompanying drawings, and to the letters of reference marked thereon, which form a part of this specification.

This invention relates to improvements in 15 registering mechanism and has for its object a mechanism whereby a plurality of independently rotatable shafts may each actuate independent registers of a combined registering mechanism and each of which carries from a lower to a higher denomination.

It is a further object of the invention to 20 provide a mechanism whereby a plurality of independently rotatable shafts each appropriated to an order of digits each actuates a corresponding register, and afford connection 25 between said mechanisms whereby co-acting and coöperating means transfer the amount registered on each lower denomination register to a register for each higher order.

It is an important object of the invention 30 to afford mechanism whereby proportional fractional rotation of a shaft or series of independent shafts shall each register upon a suitable mechanism a number indicating the extent of its rotation to afford in connection therewith mechanism for returning the shaft after each record to its normal position preparatory to another count.

It is a further object of the invention to 40 afford mechanism rotative in character for actuating as many recording mechanisms as there are rotative or partly rotative shafts and to afford coacting mechanism to trans- 45 mit the movement of said shafts to the register the part of which are firmly locked from movement except when engaged in actuating its own particular register or carrying from that register to one of a higher 50 order.

The invention is shown embodied in connection with the cash register the subject of my prior application for patent filed on the

29th day of December, 1906, Serial No. 350,057, though obviously it is capable of adaptation for any type of cash registers and in many devices other than cash registers.

The invention consists in the matters hereinafter described and more fully pointed out and defined in the appended claims.

In the drawings:—Figure 1 is a front elevation of a cash register used in connection with a device embodying my invention. Fig. 2 is a top plan view of the same with the casing removed and with parts broken away. Fig. 3 is a side elevation of the same with parts omitted. Fig. 4 is a horizontal central section taken along the dial shafts with the registering mechanism secured in position. Fig. 5 is a central vertical section taken along the dial shafts. Fig. 6 is a side elevation of the registering mechanism. Fig. 7 is a section taken on line 7—7 of Fig. 5. Fig. 8 is a section taken on line 8—8 of Fig. 5. Figs. 9, 10 and 11 are details illustrating the operation of a part of the mechanism for actuating the visible signals. Fig. 12 is an enlarged vertical section of one of the pivoted supports for the pawl bars. Fig. 13 is an enlarged detail of one of the toothed wheels or cams. Fig. 14 is an enlarged top plan view of one of the dial shaft gears with the lifting cam and stops thereon. Figs. 15 and 16 are details of the locking means for the dials. Fig. 17 is an enlarged section taken on line 17—17 of Fig. 6. Fig. 18 is an enlarged section taken on lines 18—18 of Fig. 6. Figs. 19 to 24 inclusive are enlarged sections taken on correspondingly numbered lines on Fig. 6 and illustrate adjustment operation. Fig. 25 is an additional detail of one of the locking pawls. Fig. 26 is a section taken on line 26—26 of Fig. 25. Fig. 27 is an enlarged fragmentary plan view of the yoke and springs for supporting the pawl bars when displaying the visible signals. Fig. 28 is an enlarged fragmentary detail of the governor shaft and one of the gears. Fig. 29 is an enlarged fragmentary longitudinal section of the transmission shaft and the mechanism carried thereon. Fig. 30 is a fragmentary longitudinal sectional view of the register shaft and gears. Fig. 31 is an enlarged fragmentary detail of the bell cranks

for elevating the visible signals. Fig. 32 is a front elevation thereof. Figs. 33 and 34 are enlarged details of the arm or lever carrying the visible signal. Fig. 35 is an enlarged detail in section of one of the spring pressed finger pieces set in each dial.

- As shown in said drawings: the mechanism is mounted upon a base A, within a suitable removable casing and is supported 10 within a frame consisting of end plates *a* and *a'*, which are rigidly secured to the base plate A. Journaled centrally on said end frame members and supported upon suitable bearings, is a shaft B, which protrudes 15 through the front frame plate *a'* and a dial B' is rigidly secured thereon having marked at equal distances apart near its periphery, the numerals and signs \$1, \$2, \$3, \$4 and \$5, reading from the bottom upward. Of 20 course any desired number of dollars, to and including nine dollars may be indicated thereon. As shown, a standard B² is supported on the base and affords a support for the end of said shaft B. Said shaft B is 25 journalled near its middle portion on an upright or standard *b*, supported on the base plate A', as shown in Fig. 5. Rotatively mounted on said shaft concentric therewith and extending inwardly thereon, from 30 the front end, is a tubular shaft C, having a dial C' thereon, similar to the dial B', and rotative around the same and marked consecutively on approximately half its periphery to indicate dimes from 10 cents to 90 35 cents, inclusive, and mounted to rotate on said shaft C, is an outer tubular shaft D, having a dial D', rigidly secured thereon, and marked 1 to 9 inclusive on a semi-circle to indicate pennies. Said dial is shaped to 40 fit around the dial C'. All the dials are arranged with their faces in the same vertical plane as shown in Figs. 1 and 4. Beneath the numeral 1 on the dial D' and at the same distance therefrom, as the numerals 45 from each other, is marked "No sale." As shown said numerals on each dial are marked upon a circular button *d* secured in suitable sockets in the dials and which are made of cast or pressed metal, or any material suitable for the purpose, and a spring 50 *d'* shown in Fig. 35, normally holds the other face of said button flush with the face of the dial but permits the same to be pushed inwardly to enable the finger to engage in the socket to rotate the dial.
- Rigidly secured on the shafts B, C and D are cams or wheels, such as shown in Fig. 1², and indicated as a whole by B³, C³ and D³, for the respective shafts, these 55 as shown, are provided each with a single angular tooth *b*⁶—*c*⁶—*d*⁶. The number of said cams on each shaft is the same as the number of stations on its dial, in other words there are ten on the shaft D, nine 60 on the shaft C and five on the shaft B, and
- these are arranged and rigidly secured so that the teeth on each set are spaced equal distances apart in approximately a semi-circumference to correspond with the arrangement of the numerals on the dial. Said cams are 70 spaced a slight distance apart on the shaft, by means of a relatively thin plate *a*¹⁰ of metal engaged between adjacent cams, as shown in Fig. 4, and are rigidly secured on their shafts by keys or by a projection suitably positioned with a central bore one of which *x*²⁰ is shown in Fig. 13. They are also secured in place by means of nuts *d*⁵—*c*⁵—*b*⁵, threaded on the respective shafts and between which and the cams, on each shaft is 75 rigidly secured a gear wheel *b*⁴—*c*⁴—*d*⁴.
- Rigidly secured to the front and rear frame plates *a*—*a'* by means of its downwardly bent ends *c*—*c'*, as shown in Figs. 3, 7 and 8, is a rigid horizontal bar E, which is positioned at the left of and above the dial shafts, and a central depending bracket *e*¹⁰ is secured at about the middle thereof, and extending through said bracket and the end *e'* of said bar, is a non-rotative shaft *e*². 85 Pivoted on said shaft *e*² between the bracket *e*¹⁰ and the end bracket *e'* are inwardly directed arms *e*³—*e*¹¹, which extend to near and above said gears or said dial shafts, and are connected intermediate their ends by a 90 rigid horizontal bar E' on which just at the rear of the gears *d*⁶ and *c*⁶ are secured inwardly directed rigid arms E². These are in length equal to the projection of the arm *e*³ beyond the bar E' and each is provided with 95 a downwardly directed spring controlled pawl *e*⁴, at its extremity positioned to be engaged by a cam *e*⁵ secured on the rear side of each gear wheel, on each dial shaft, and which acts to lift all said arms simultaneously as shown in Figs. 7, 8, 9, 10 and 11. 100 Also secured on said shaft *e*², and projecting forwardly over the bar E' are relatively broad leaf springs *e*⁶, the inner edge of which is bent downwardly at a right angle 110 for its entire width affording a detent *e*⁹. Said spring plates are held in firm bearing upon the bar E' by means of springs *e*⁷, as shown in Figs. 3, 7 and 8, which bear against the same and beneath a top plate *a*⁴. Rigidly secured on said arms *e*³ and *e*¹¹ are upwardly directed inwardly hooked arms *e*⁸, which engage over the plate *a*⁴, at their upper ends and limit the downward movement of the arms, but permit the arms to 115 swing upwardly against the tension of the spring.
- Hinged on the base plate A' opposite each set of cam wheels is a standard shown more plainly in Figs. 9 to 12 inclusive. 120 This, as shown, comprises a projection or boss *f*, rigidly secured to the base plate, and on the top of which is hinged a tubular body F, as shown in Fig. 12, in which is slidably engaged a cylindric and threaded 125
- 130

stem f' , held from turning therein by means of a pin f^2 , secured in said stem and extending into a longitudinal slot, in said tubular body. Said stem is adjusted as to height by means of a nut f^3 , and a jam nut f^4 , secured on said stem and bearing on said body F, and whereby the stem is supported at an adjusted height on the upper end of said body. The upper end of said stem, as shown, is provided with a head f^7 , in which is rigidly engaged an upwardly and inwardly curved blade or plate f^8 , having its upper edge f^9 , directed horizontally and longitudinally of the machine and rounded to afford a support, and of a length to extend across the face or edge of all the cam wheels in the set opposite which it is secured. Supported at their inner ends on the upper rounded edge f^6 of said hinged supports, are transversely slideable pawl bars G, which equal in number the cams in each set and are positioned respectively directly above each of the cam wheels. Each is provided at its inner extremity with an upwardly directed projection or tooth g , adapted to engage beneath and behind the downturned lip or detent e^9 of the leaf spring e^6 . As shown also each is provided near said end on its under side with a notch having downwardly and outwardly inclined sides toward the adjacent end of the bar, and the other side thereof affords a somewhat rounded shoulder g^2 . Directly above each cam wheel a downwardly extending tooth g' is provided on each pawl bar, adapted to be engaged only by the tooth on the corresponding cam wheel. As shown also said pawl bars between the tooth on each, and the shoulder g^2 , is cut away to afford an inclined face for engagement by the teeth on the cams as the same are rotated forwardly thereby lifting the ends of the pawl bars. At the opposite end said pawl bar is pivotally engaged and supported upon a lever G', the upper end of which projects above the top plate a^4 . As shown also a comb g^3 is secured beneath the top plate, and the teeth thereof extend downwardly between the said pawl bars, holding the same positioned each directly above its actuating cam. Arranged obliquely on the upper side of the top plate as shown in Fig. 2, is a set of bell cranks H, ten in number corresponding with the number of cams on the penny shaft D, and rods h' connect the forwardly directed arms h with the upper end of the lever G', before described. The opposite arm h^2 , which is directed transversely the machine, is pivotally engaged by a rod h^3 , which leads rearwardly, and is adjustably connected with a downwardly directed arm h^4 , of a lever h^5 which is pivotally supported at the rear end of the frame, as shown in Fig. 5. Said levers extend forwardly through a vertical comb h^6 , and are each provided at their

forward ends with an upwardly directed arm h^7 , on the upper end of which is a tablet h^8 , which may be as shown of circular or any desired or suitable form and on the front and rear faces of which there is marked or indicated the numeral, sign or other representation or representations contained upon the button of the dial, from which said pawl is actuated. There are, of course, as many of said levers as there are stations on all the three dials including the "No sale" station. Inasmuch as ten of said levers are appropriated to penny dial, nine to the dime dial and five to the dollar dial, there are ten of said bell cranks on the series H, for pennies, nine in the series H¹, for the dimes, and five in the series H² for dollars, each of which when actuated by its pawl bar acts to elevate the proper tablet to afford a visible signal in the view aperture A⁴, at the top of the case. Inasmuch as the tooth on the cam corresponding in position with the numeral on the dial it is desired to register is directly in front of the tooth g' on the pawl bar, said teeth on the cams engage and successively lift the pawl bars, against the tension of their springs g^9 , shown in Figs. 7 and 8, until the completion of the forward movement or count of the dial. When the dial is released at the end of the forward movement, the tooth d^4 , c^4 or b^4 on the cam, corresponding with the count to be represented and which has just passed and is in advance of the tooth g' on the corresponding pawl bar, immediately engages said tooth g' as the dial returns to its normal position. Said pawl bar is moved laterally thereby pushing the hinged support F, therewith and elevating the adjacent ends of the remaining pawl bars (owing to the inclined surface of the notch in each of said pawl bars in which the top of the support rests) to a height to let the remaining teeth on said cams pass beneath without contact. The end of the positively actuated pawl bar passes beneath the spring plate e^6 , to be retained by the detent thus elevating its tablet into view and supporting the same until a dial is again actuated when the cam e^5 engages the pawl e^4 , on the end of one of the cams or arm e^3 or E², lifting the same and releasing the pawl bar and permitting the visible signal to fall.

Of course any suitable mechanism may be provided to return the dials and cams to position for the next count. For this purpose, however, gears I, are journaled on a standard i, rigidly secured on the base plate A', and in mesh with the gears d^4 — c^4 — b^4 respectively, for each set of cams, and secured to the axle or shaft for each said gears and to said standards i are strong coiled springs i' which are wound up by rotation of the respective dial shafts when actuated by their dials, and act to quickly return the dial ac-

tuated to normal when released. As shown in Fig. 8, means are provided to insure the dial always stopping at normal. For this purpose a stop i^5 , which may be integral with the cam projection e^5 , is rigidly secured on the dial shaft gear $b^4-c^4-d^4$ and engages the top of the appropriate standard when the dial is at normal. In the same manner the opposite end of said stop or any suitable stops i^6 may be provided on said gears to engage the standard i or any suitable rigid part of the machine, to limit the downward movement of the dial when actuated to make its maximum count. As shown, both said stops 10 and the cam projection e^5 are formed from single plates of the proper size and shape and rigidly secured on the rear side of each gear. The return movement of the dial and the cams under the action of said springs, is also 15 regulated to prevent pounding or injury to the machine. For this purpose a governor is provided comprising a shaft J journaled on suitable standards $J'-J^2-J^3$, secured on the base plate A' and gears j are rotatively 20 secured thereon in mesh with the positively driven gears I , for each dial. As shown in Figs. 4, 7, and 28, a disk j' , is rigidly secured on each gear j and bearing against the face of said disk is a ratchet j^3 , rigidly secured on 25 said shaft J , and which is engaged by a spring controlled pawl j^2 , on said disk j' , thereby rotating the governor shaft J , as the dial returns to position. On the rear end of said governor shaft J , is secured a gear j^4 , which meshes with a pinion j^5 , secured on the same shaft with a gear j^6 , which in turn meshes with a pinion j^7 , which drives a centrifugal governor J^5 , of any suitable kind, and which is provided at one end with 30 a friction brake wheel j^9 , adapted to be engaged by a shoe j^{11} as shown in Fig. 3. Said governor is obviously driven on the return movement of the dials when any one or more of the dials are actuated and acts to retard 35 the return movement of the dial to prevent shock due to violent impact of the stops i^5 , on the standards i though of course if necessary said governor may be driven when the dials are rotating in either or both directions.

Accurate mechanism for positively registering each transaction and at any time showing the sum of the transactions of the day or a longer period is provided. For this purpose a registering mechanism is secured in the side of the machine opposite the governor upon a removable base plate M , which is bolted or secured on the base plate A' and extends for nearly the length of the machine. Secured thereon are uprights or standards $m-m'$ and m^2 which project thereon upwardly and inwardly toward the gears $b^4-c^4-d^4$ on the dial shafts. Rigidly secured on said base plate M , between the standards $m-m'$ and m^2 and

the dial shafts are standards $l-l'$, and rigidly secured therein is a horizontal shaft L , as shown in Figs. 4, 6 and 29. Journaled thereon adjacent the standard l , is a rotatable sleeve N , provided at its end 70 adjacent the standard with an integral gear n , which meshes with the penny gear d^4 , on the dial shaft D . Also integrally secured on said sleeve is a crown gear n' provided with nine teeth spaced 36° apart, to indicate 75 the significant digits on the penny dial and having one vacant space for the "No sale" station on said dial. Said teeth n^2 , as shown, comprise rounded pins, set in the face and near the periphery of the gear and projecting toward the rear, as shown in Fig. 21. At the rear end of said sleeve is provided an integral disk n^3 , provided on its periphery with an upwardly projecting tooth n^4 as shown in Fig. 6, the action of 80 which will be later described. At the rear end of said sleeve a collar n^5 is rigidly secured on the shaft L and together with the standard l holds said sleeve always in operative position with the gear n , thereon, in 85 mesh with the penny gear d^4 .

In the same manner a sleeve O is rotatively secured on said shaft L on the front side of the standard l' , and is provided at its forward end with an integral gear o , which 90 meshes with the dime gear c^4 , on the dial shaft C . At the rear of gear o is a crown gear o' corresponding in all respects with the crown gear n' before described and provided as shown, with nine teeth o^2 , similar 95 to those thereon. At the rear end of the sleeve is a disk o^3 , provided with an upwardly directed tooth o^4 , corresponding with the tooth n^4 on the disk n^3 , said sleeve is held at all times in operative position with its 100 gear o meshing in the dime gear c^4 , by means of a collar o^5 and the standard l' .

At the rear side of the standard l' is secured a sleeve P , provided with a gear p thereon which meshes with the dollar gear b^4 , on the dial shaft B and at the rear end of said sleeve is an integral crown gear p' as shown in Figs. 4 and 29, provided with inwardly directed teeth p^2 , corresponding in 105 number with the number of stations on the dollar dial B' , or as shown five, which are spaced equal distances apart near the periphery of the gear.

Journalized in the standards $m-m'-m^2$ and a standard or post m^3 at the rear end of the plate M , is a horizontal shaft Q , at approximately the same level with the shaft L and which is the registering shaft for pennies. Secured on the end of the shaft Q , beyond the standard m , is a ratchet q' having its teeth directed upwardly and inwardly, and which are engaged by a spring pressed pawl q secured on the standard m , whereby the shaft Q is held from rotation except that outwardly and downwardly or 115

125

130

in other words in the direction of rotation of the penny dial shaft D, in ringing up the transaction. At the rear side of said standard m , and rigidly secured on said shaft Q is a wheel N' , as shown in Figs. 21 and 30 having pivoted thereon ten radially and outwardly directed projecting teeth n^6 which extend into position to be engaged by the teeth n^2 of the crown gear n^1 . As shown 5 more plainly in Fig. 21, said teeth n^6 are each provided with an integral inwardly directed tail n^7 , adapted to engage on a pin n^8 , positioned adjacent to the pivot to hold said teeth from swinging in their pivot when 10 engaged by the teeth n^2 , on the crown gear during the rotation of the dial to make its count, thereby rotating the shaft Q but which swing downwardly on their pivot permitting the teeth n^2 to pass the same, as the 15 dial and crown gear return to normal position. As shown, a spring n^9 is secured on each tooth and acts to hold the same normally directed outwardly, in position to be engaged with the teeth of the crown gear. 20 At the rear end of said shaft Q is a penny indicating wheel q^2 which is rigidly secured thereon. This, as shown, in Fig. 3, is provided on its periphery with the ten digits arranged thereon equal distances apart and 25 increasing upwardly and inwardly toward the dial shafts.

Rotatively secured on the shafts Q is a tubular shaft Q' which extends through the standards m' and m^2 and the rear end of 30 which bears against the penny indicating wheel q^2 . Secured on said shaft at the front side of the standard m' is a ratchet wheel o^7 with its teeth directed oppositely from those of the ratchet wheel q^1 , secured on the shaft 35 Q, or in other words secured to rotate the shaft Q' upwardly and inwardly, or on the return movement of the dial C'. Pivoted on the standard m' is a spring controlled pawl o^8 which engages said ratchet wheel and acts 40 to hold the shaft Q' from rotation when the dial is moving downwardly in counting. Rigidly secured on said shaft Q' on the rear side of the standard m' is a ratchet wheel O' having its teeth directed toward the direction of the rotation of the shaft in recording 45 and provided with ten outwardly and radially directed teeth o^{10} corresponding in all respects to the teeth n^8 on the wheel N' , before described, excepting that said ratchet 50 teeth are free to swing upwardly when engaged by the teeth o^2 of the crown gear o^1 , but are rigidly locked from downward movement on the ratchet wheel O' by means of pins o^{11} set in the face of said wheel and engaged 55 by a tail piece o^{12} on each tooth so that as the dime dial C' returns to normal, rotating the crown gear o^1 thereby, each of the teeth on said ratchet crown gear successively engage one of the pivoted teeth on 60 said ratchet wheel O' rotating the shaft Q to make the count. At the rear end of said shaft and adjacent the penny indicating wheel q^2 is a dime indicating wheel q^3 having marked upon its periphery equal distances apart, the ten digits which inasmuch 70 as the shaft Q' rotates oppositely from the shaft Q, are arranged oppositely on said wheel from those on the penny indicating wheel, reading from the top downwardly and outwardly. 75

Mounted to rotate on the tubular shaft Q' is a tubular shaft Q^2 which projects through the standard m^2 and is provided at its forward end with a ratchet wheel q^4 the teeth of which are directed upwardly and inwardly and a spring pressed pawl q^8 is pivoted on the standard m^2 and engages said gear to hold the shaft from rotation, when the dial is returning to normal position. A ratchet wheel P' is secured on said shaft, at 80 its rear end, and pivoted thereon, as shown in Fig. 17, are ten pivoted outwardly directed teeth p^5 . Said teeth project radially beyond the periphery of the ratchet wheel P' into position to be engaged by the teeth p^2 on the crown gear p^1 , and are free to swing downwardly as said crown gear rotates during the return of the dollar dial B', to normal, but are rigidly held against the upwardly rotation of said gear, as the dial 90 turns downwardly in making the count. Inasmuch as there are ten of said pivoted teeth on said ratchet wheel, each tooth on the crown gear, rotates the shaft Q' one tenth of a revolution in consequence one complete 100 rotation of said shaft indicates ten dollars.

On the inner end of the tubular shaft Q^2 is secured a gear q^5 which meshes with a gear q^6 of equal size, as shown in Fig. 6, secured on the shaft of a Veeder register or 105 any other suitable register Q^4 , secured on said base plate M. Secured also on the Veeder shaft back of the gear q^6 , is a milled wheel q^7 of slightly greater diameter adapted to be manually engaged to turn the recorder back to O. The Veeder is slidably secured on said base plate M, by means of a plate r which slides on said base plate as shown in Fig. 24, and on which is secured a bracket r' , in which is secured the inner end 110 of a cam shaft R which extends through the base of the Veeder and which is provided on its outer end with a milled wheel r^2 , whereby the same may be rotated. Said shaft R, is provided near its inner end with a cam r^3 , 115 and at its extremity with a collar r^4 . When the Veeder is pushed inwardly until the standard n' engages the block r^5 and the shaft R rotated, the cam r^3 rigidly engages behind the block r^5 which is secured to the 120 base plate M, and thereby rigidly holds the gears q^5 and q^6 in mesh. As shown a spring r^7 is secured on the base plate M, and bears against the end of the slide bars r , and acts 125 when the cams are released to throw the 130

Veeder outwardly and the gears out of mesh thereby permitting the register to be reversed or set back.

Obviously the penny register or indicator wheel must rotate continuously with the rotation of the penny dial D' and the dime wheel must rotate continuously with the dime dial C' and the Veeder will register dollars accurately when actuated by the dollar dial B'. It is necessary however, to transfer or carry each ten cents counted on the penny register wheel q² to the dime register wheel q³ and all tens counted on the dime dial or both penny and dime dials must be counted as dollars. In other words each complete rotation of the penny indicator wheel q² must produce one tenth of a revolution on the dime wheel q³ and one complete rotation of the dime register q³ may count one on the register or Veeder.

As shown, and for the purpose of transferring the tens from the penny register to the dime register, a lever S is pivotally supported at its upper end on the standard m' and its lower end, as shown in Fig. 22, extends to near the base plate M and is curved outwardly and provided with a horizontal forwardly directed stud s thereon. Said lever is engaged by a spring S⁵ which holds the lower end swung outwardly. Rigidly secured on the shaft Q is a collar s' provided with a radially directed arm s², of a length to engage said stud s when said lever is at its proper position in the rotation of the shaft Q, that is to say after nine cents have been indicated on the penny indicator wheel q². Pivotally connected in the middle of said lever is a bar S' which extends outwardly through a suitable support s³ on the standard m' and a pawl s⁴ is pivotally secured on said bar, and engaged to rotate the ratchet o⁵ on the shaft Q' (on which is the dime indicator wheel q³) when another penny is registered completing the counting of ten cents.

Before the shaft Q can rotate, however, the ratchet wheel O' must be released from its pawl s⁷. Journalized near their tops on the standards m—m' is a shaft S² and rigidly secured thereon is a depending arm S³, which is bent inwardly at its extremity, and into position to be engaged by a finger s⁸ secured in the collar s' at an angle with the arm s², so that said finger engages and lifts the arm S³, just before the arm s² engages the stud s on the lever S. On the other side of the plate m' a bell crank is pivotally supported one end s⁹ of which is shaped to afford a pawl, which is firmly held in engagement with the teeth of said ratchet O', by means of a spring s⁸ as shown in Figs. 18 and 19, the other end S¹⁰ of said bell crank depends between the ratchet wheel O' and the standard m' and an inwardly directed finger s⁹ is pivotally engaged thereon at its

end, and is rigidly held from swinging downwardly on said arm by abutting against a shoulder s⁶ thereon as shown in Fig. 25 and is held against upward movement by a spring s¹⁵. Said finger projects into the path of the teeth o² on said crown wheel o', so that the teeth of the crown gear engage said finger lifting the pawl s⁷ just before they engage said pivoted teeth to rotate the ratchet wheel and shaft Q'. Carried on the shaft S² is a curved arm s¹¹ slotted at its lower end, as shown in Figs. 18 and 19, and which engages a pin s¹², on the end s⁷ of said bell crank so that when the finger s⁸ on said collar s' engages the lever S³ rotating the shaft S² it lifts said arm s¹¹, lifts the pawls s⁷ and the ratchet wheel O' is free to rotate the shaft Q' just before the pawl s³ is actuated, thereby registering one dime on the register wheel q³ and turning the penny indicating wheel to o.

Means are provided for recording one, on the Veeder for each ten times turned up on the dial C' or D', or both conjointly. For this purpose a shaft T is journalized at the top of the standard m—m' and m² and depending therefrom at its ends are arms t—t' at the lower end of which is journalized a shaft T², the end of which projects from near the standard m to near the standard m². Rigidly secured on said shaft T² is a bent lever T' the inwardly directed end of which is provided with a downwardly directed finger t⁴ controlled by a spring t² secured thereon and on the lever to hold the same with its end directed downward. Said finger may swing inwardly only by extending said spring. The outer end of said lever as shown extends laterally outward, between standards m' and m² and near its periphery curves or is offset downwardly as shown in Figs. 18 and 19, affording a cam surface. Secured between the standard m' and m² is a shaft t⁶ which serves as a stop to limit the upward movement of the outer end of said lever T' and on which is a roller t¹⁵ to facilitate movement of the lever. As shown, a pintle t⁷ extends through the inner end of said lever T' and carries the finger t⁸. Rigidly secured on a bar t⁸ secured on the shaft T² is a depending finger t⁹ as shown in Fig. 22, and which depends into position to be engaged by the finger or tooth n⁴ on the disk n³, of the transmission shaft actuated in registering pennies and the finger t⁴ depends as shown in Figs. 18 and 19 into position to be engaged by the finger or tooth o⁴ on the disk o³ for registering dimes. Both are normally supported out of engagement with said teeth, and are capable of being engaged thereby only when the outer end of the lever T' is elevated, as shown in Fig. 19. Means are provided for elevating said lever T' comprising a collar t¹² rigidly secured on the shaft Q', and on which is

provided a curved arm t^{13} , which is so positioned as to lift the outer end of said lever, as shown in Fig. 19, only when the dime registering wheel q^3 indicates nine opposite 5 the Veeder or register, in other words, when a count of one or more on the dime dial, whether made by actuating the penny or dime dial should count the tenth dime or one dollar. When this occurs on the next count 10 the rotation of the shaft Q' elevates the lever T' as before described throwing the fingers t^4 and t^9 downwardly into position to be engaged either by actuation of the penny dial or the dime dial. Said lever is supported 15 in said position between coacting springs t^{14} , shown in Figs. 6, 18, 19, which as shown is provided with a longitudinal rib t^{16} to enable said springs to hold the same better against the tension of the spring t^{17} , which 20 acts to throw said lever down and a stop t^{20} limits the return movement of the lever T' to normal and supports the same in said position. When the dials are next actuated the finger o^4 or n^4 on the transmission shaft 25 corresponding with said dial engages the finger t^4 or t^9 and carries the lever T' outwardly thereby rotating the ratchet q^4 and shaft Q^2 . The shaft T , is normally held from rotation by means of a pulling spring 30 t^{18} , secured on an arm t^{19} , secured thereon as shown in Fig. 6, and is normally supported on a stop t^{20} set in the standard m .

Rigidly secured on the rear end of said shaft T is a depending bar U , as shown in 35 Fig. 20 and pivotally supported thereon is a spring pressed pawl u which engages a pin on a pawl lever U' the lower end of which engages the ratchet wheel P' for the dollar register, and which normally holds the 40 same from movement. As shown, a finger u^2 is pivoted on the lever of said pawl U' corresponding with the finger s^9 on the lever S^4 , and the pawl s^9 serves the same purpose for the crown gear o' . When said shaft T 45 is rotated as heretofore described said arm U swings outwardly releasing the pawl U' from the ratchet P' just as the forward swing of the shaft T^2 on the arms $t-t'$ carries the pawl t^3 forwardly to rotate the dollar shaft Q^2 . The moment the ratchet has 50 been turned one notch, or one tenth of a revolution of the shaft, the tooth o^4 or n^4 slips past the finger t^4 or t^9 and instantly the spring t^{18} acts to return said shaft T to 55 normal position retracting the lever T' and the pawl t^3 and returning the pawl U' into positive engagement with the ratchet wheel P' . Inasmuch as the dime register acts on the return movement, the forward movement 60 of the dials B' and D' in carrying the penny and dollar is accomplished independently of the normal operation of the mechanism in recording dimes.

Means are provided for locking the dials 5 from movement. For this purpose a stand-

ard X is supported on the base plate A' , adjacent the end frame plate a' and pivoted on a foot piece x , secured on the base is an upwardly directed arm x' which at its upper end protrudes through a slot in the end 70 of a bolt X' . Said bolt extends through the frame plate a' and is adapted to engage between the spider arms of the dials adjacent the shafts therefor. A pin x^2 extends through the head of said bolt and engages 75 in a slot in the standard X to keep the bolt from turning, and a shaft x^3 which is rigidly engaged to the arm x' serves as the pivot and by its rotation shoots the bolt or retracts it. 80

The operation is as follows: In registering pennies rotation of the dial D' acts first to rotate the gear d^4 and thence by means of the crown gear n' and wheel N' having pivoted teeth, which rotates the register shaft Q , to indicate on the penny wheel indicator q^2 , opposite the Veeder, the amount being indicated as the dial is turned downward. When the penny or any dial is released the return movement thereof causes 90 the tooth on the cam wheel $B^3-C^3-D^3$ which is secured on the corresponding dial shaft to actuate the pawl bar G , corresponding in position with the number to be registered which moves the support f^6 to elevate the 95 other pawl bars out of the path of the teeth on their respective cams. The pawl bar G engaged by the tooth is carried beneath the spring detent e^6 which engages the same elevating its visible signal into view at the top 100 of the machine and indicating the amount purchased. In the same manner the dime dial C' acts to give the signals, and registers on the wheel q^3 . When the number indicated on the penny dial is sufficient to 105 make one dime, this is carried to the dime register wheel opposite the Veeder. This is accomplished by the arm s^3 being swung forward, releasing the ratchet wheel O' when the arm s^2 engages the stud s on the 110 lever S thereby actuating the pawl s^4 , rotating the dime register shaft one tooth or one tenth of a revolution on the down pull of the dial D' while all other tens are counted on said registering wheel q^3 during 115 the return movement of the dime dial C' . Should the actuation of the penny dial D' complete a dollar, the action is the same, the rotation of the shaft Q' , however, has brought the bent arm t^{13} beneath and has 120 lifted the lever T' thereon throwing the finger t^6 down. This is engaged by the tooth n^4 on the disk n^8 , retracting the pawls s^7-u' rotating the dime registering wheel to O and rotating the shaft Q^2 one tenth of 125 a revolution, thus counting one on the Veeder. Should the dime dial C' be next actuated none of the mechanism for the dollar register or the penny register is actuated, inasmuch as each of the dials is set 130

cured on an independent shaft and the register gears are also each on an independent shaft. The count is made upon the return movement of the dial C'. The rotation 5 of the gear c⁴ actuates the crown gear o' in turn rotating the shaft Q' and indicating the same upon the dime register wheel q³ until nine dimes have been registered. When this occurs the arm t¹³ assumes a position 10 shown in Fig. 19, elevating the lever T' and throwing the fingers t⁴ and t⁹ downwardly to be engaged by the tooth o⁴ or n⁴ with the results heretofore described. When the dial is released the return movement 15 thereof rotating the crown gear o' and disk o³ carries said levers T' forwardly releasing the pawl U' for the dollar shaft Q² and likewise the pawl s' on the dime shaft is released, and the pawl t³ engaging the ratchet 20 q⁴ and rotates the shaft Q² one notch.

It is obvious any amounts rung up on the dollar dial B' will be recorded on the Veeder independently of any movement of the dime or penny dial C'—D' or the registering means 25 therefor. The return movement of the dials under the action of the springs therefor and the movements of the registers are perfectly controlled at any desired rate of speed by means of the centrifugal governor, and this 30 may be set to vary the tension thus causing a relatively slow or a very quick return just as desired. Of course from the construction described, the dials and indicators in each instance return back to neutral position, inasmuch as the stops provided for that purpose 35 on the gears b⁴—c⁴—d⁴ engage on the corresponding standard i.

Many details of construction may be varied and obviously any equivalent mechanism 40 may be substituted to effect the transfer from the penny and dime registers to the dollar register or Veeder. Inasmuch as I have shown but one construction embodying my invention, I do not purpose limiting this 45 application for patent otherwise than necessitated by the prior art, as it is evident that variations of details of construction may be almost indefinite in number without departing from the principles of my invention.

50 I claim as my invention:

1. A registering device comprising rotative registering members each adapted to register only when rotating oppositely from the adjacent members and mechanism for 55 transferring a count from all the lower denomination registering members acting jointly to the highest denomination register.

2. A registering device comprising rotative registering members each adapted to 60 register only when rotating oppositely from an adjacent member and mechanisms for transferring a count from each lower registering member to the next higher registering member and to transfer a count from a

combination of the lower registering mechanisms to the highest registering mechanism. 65

3. A registering mechanism embracing registering devices each operating in an opposite direction from the adjacent lower denomination device, a shaft and independent 70 mechanisms on said shaft all rotatable independently and one for actuating each registering device to register the proper amount.

4. A registering mechanism embracing 75 registering devices each operating in an opposite direction from the adjacent lower denomination device, independent mechanisms one for actuating each registering device to register the proper amount, means for locking each registering device from 80 movement in a direction reverse to its registering movement and means normally locking part of the registering devices from registering movement.

5. A registering mechanism embracing 85 registering devices each operating in an opposite direction from the adjacent lower denomination device, independent mechanisms, one for actuating each registering device to register the proper amount, independent 90 means for normally locking all registering devices except the lowest denomination from registering movement, independent means for permanently locking each registering device from movement reverse to registering 95 movement and an independent mechanism for adjusting each normally locking mechanism out of locking engagement.

6. In a device of the class described registering devices, an independent shaft for 100 each, rotatable mechanisms, one for actuating each registering device, means for actuating the highest denomination registering device independently of the appropriate rotatable mechanism, normally elevated means 105 connected therewith, means for lowering said normally elevated means prior to transferring a count to the highest denomination register and means for actuating said means when lowered to transfer a count to the 110 highest denomination registering device.

7. In a device of the class described oppositely rotatable registering wheels, reversely marked on the periphery with the significant digits, a locking mechanism for each 115 wheel adapted to lock the same from movement in each direction, means for actuating each registering wheel and moving the locking mechanism for each register out of operation for the wheel to register. 120

8. In a device of the class described oppositely rotatable registering wheels reversely marked on the periphery with significant digits, an independent mechanism locking each wheel from registering movement except the lowest denomination wheel 125 and a single rotatable element for actuating each registering wheel and adjusting the

locking mechanism for its registering wheel out of operative position prior to rotating the same.

9. In a device of the class described oppositely rotatable toothed registering wheels, means for transferring a count from a lower to a higher denomination wheel, a lock for each registering wheel after the first and engaging the teeth thereof, and means for 5 oscillating the appropriate lock to engage successive teeth of its registering wheel and to actuate the registering wheel one tooth between each oscillation of the lock.

10. In a device of the class described concentric shafts, a toothed registering wheel 15 each means for actuating each registering wheel and locking mechanism for each registering wheel after the first successively oscillated by the means for actuating the 20 registering wheel adapting the registering wheel to advance one tooth between oscillations.

11. A registering mechanism comprising 25 rotatable registering devices appropriated to different money denominations, a transferring mechanism for each registering device, a total adding register geared to rotate with the highest denomination registering device and mechanism for shifting the total adding 30 mechanism to throw the geared connections out of operation to permit the total register being quickly set back to zero.

12. A registering mechanism comprising 35 independently rotatable registering devices appropriated to different money denominations, mechanism for transferring a count from one registering device to another, an adjustable standard, a total adding register connected with the highest denomination 40 register adapted to register one count for each partial rotation of the highest denomination registering device and means for adjusting the standard to disconnect the total adding register with the highest denomination 45 registering device.

13. A registering mechanism comprising 50 independently rotatable registering devices appropriated to different money denominations, mechanism for transferring a count from one registering device to another, a total adding register actuated to register one count for each partial rotation of the highest denomination registering device and oppositely rotatable counting wheels axially 55 aligned with all the registering devices and one for each registering device except the highest denomination register and reversely marked on the periphery with digits and rotatable with the respective registering device.

14. In a registering device rotatable dollar, dime and penny registering elements, each independently rotatable, a total adding register actuated by rotation of the dollar 60

registering element and registering wheels 65 in alinement with the total adding dollar register appropriated respectively to dimes and pennies and connected directly with the respective dime and penny registering element adapted to rotate therewith to indicate the total cents registered in alinement with the reading on the dollar register.

15. In a device of the class described oppositely rotatable register wheels reversely 70 marked on the periphery with the significant digits and appropriated to dimes and pennies, a total adding register for dollars, an independent mechanism for registering dollars to the total adding register, and independent dime and penny mechanisms 80 adapted to register dimes and pennies to the respective register wheels.

16. In a device of the class described rotatable concentric shafts register wheels thereon marked on the periphery with the 85 significant digits and appropriated to dimes and pennies, a total adding register for dollars, an independent mechanism for registering dollars to the total adding register, independent dime and penny mechanisms 90 on said concentric shafts adapted to register dimes and pennies to the respective register wheels and means for transferring a count of one to the total adding dollar register when the combined sum indicated by the 95 register wheels equals one dollar.

17. In a registering device a total adding dollar register, oppositely rotatable penny and dime registering wheel each having digits marked on the periphery thereof, registering mechanisms appropriated to dollars, dimes and pennies respectively and each registering directly to the appropriate register wheel or total register and means for registering a dollar on the total register 100 for each dollar registered on the dime and penny counting wheels.

18. In a device of the class described a total adding register for dollars, concentric shafts register wheels thereon adjacent each 110 other marked with digits and appropriated to dimes and pennies respectively independently rotatable mechanisms, one mechanism on each shaft adapted to rotate the wheels oppositely in registering sums less than one dollar, and means for registering dollars to the total register.

19. In a device of the class described a total adding register for dollars, register wheels marked with digits and appropriated 120 to dimes and pennies respectively, independently oscillatable mechanisms adapted to rotate the wheels oppositely in registering sums less than one dollar means for registering dollars to the total register and 125 a set back mechanism for setting the total register to zero.

20. In a device of the class described a

total adding register for dollars, register wheels marked with digits and appropriated to dimes and pennies respectively, independently rotatable mechanisms adapted to 5 rotate the wheels oppositely in registering sums less than one dollar, means for registering dollars to the total register, means for adjusting the total register out of operative position and means for setting the 10 same to zero.

21. In a device of the class described registering wheels, teeth pivoted to each, a stop for each tooth, a spring engaged to each tooth adapted to normally hold the same 15 projecting beyond the periphery, crown wheels, one for each registering wheel and teeth engaged to each crown wheel adapted to engage the pivoted teeth of the respective registering wheel and actuate the registering 20 wheels in one direction only.

22. In a device of the class described registering wheels appropriated to different denominations, spring controlled teeth pivoted on each wheel, means adapted to engage the 25 teeth of said wheels for rotating the wheels in registering, a register connected with each registering wheel adapted together to indicate the total sum registered and mechanism for transferring a count to the 30 highest denomination register from one of the lower registers or all the lower registers acting conjointly.

23. In a device of the class described rotatable toothed register wheels appropriated 35 to dollars, dimes and pennies, a locking mechanism for the dollar and the dime register wheels and engaging the teeth of the respective register wheel, teeth pivoted to each register wheel, springs holding the 40 teeth to extend outwardly beyond the periphery of the wheels, and crown wheels having teeth adapted to engage the pivoted teeth of the respective register wheel for rotating the same and the teeth of the appropriate 45 crown wheel adapted to operate the locking mechanism for the respective register wheel to permit the same to rotate.

24. In a device of the class described rotatable registering elements, rotatable elements 50 extending parallel therewith for actuating adjacent registering elements oppositely and automatically returning to normal position after each operation.

25. In a device of the class described registering elements arranged to register in opposite directions, mechanisms for actuating the registering elements, each in the respective direction for registering and a governor controlling the rate of movement of the 55 actuating mechanism.

26. In a device of the class described concentric shafts, a registering mechanism on each, a shaft extending longitudinally of the concentric shafts and freely rotatable 60 wheels thereon, each adapted to independ-

ently operate one of the registering mechanisms.

27. In a device of the class described concentric shafts, a registering mechanism on each, a shaft extending longitudinally of the concentric shafts, freely rotatable wheels thereon, each adapted to independently operate one of the registering mechanisms and an independent mechanism for locking each registering mechanism after the first from 75 registering movement.

28. In a device of the class described concentric shafts, a registering mechanism on each, a shaft extending longitudinally of the concentric shaft, freely rotatable wheels 80 thereon, each adapted to independently operate one of the registering mechanisms, an independent mechanism for locking each registering mechanism after the first from registering movement and each wheel adapted 85 to shift the appropriate locking mechanism out of operative position prior to operating its registering mechanism.

29. In a device of the class described concentric shafts, a registering mechanism on each, a shaft extending longitudinally of the concentric shafts, freely rotatable wheels thereon, each adapted to independently operate one of the registering mechanisms, an independent mechanism for locking each 90 registering mechanism after the first from registering movement, each wheel adapted to shift the appropriate locking mechanism out of operative position prior to operating its registering mechanism, a mechanism for 95 transferring a count from a lower to a higher denomination registering mechanism and mechanism other than the respective wheels for shifting the locking mechanism out of operative position prior to a transfer 100 from one registering mechanism to another.

30. In a device of the class described concentric shafts, a registering mechanism on each, a shaft extending longitudinally of the concentric shaft, freely rotatable wheels 110 thereon, each adapted to independently operate one of the registering mechanisms, an independent mechanism for locking each registering mechanism after the first from registering movement, each wheel adapted 115 to shift the appropriate locking mechanism out of operative position prior to operating its registering mechanism, mechanisms for transferring a count from all the lower denomination registering mechanisms acting 120 conjointly to the highest denomination registering mechanism and mechanisms for adjusting the locking mechanisms of all registering mechanisms out of locking position.

31. In a device of the class described concentric shafts, a registering mechanism on each, a shaft extending longitudinally of the concentric shaft, freely rotatable wheels thereon, each adapted to independently operate one of the registering mechanisms, an 125 130

- independent mechanism for locking each registering mechanism after the first from registering movement, and adapted to be unlocked by rotation of the appropriate 5 wheel and a transferring mechanism between each adjacent pair of registering mechanism, each adapted to act singly to transfer a count from one registering mechanism to an adjacent registering mechanism and to act 10 conjointly to transfer the sum from a plurality of registering mechanisms to the highest denomination register.
32. In a device of the class described concentric shafts, a registering mechanism on 15 each, a shaft extending longitudinally of the concentric shaft, freely rotatable wheels thereon, each adapted to independently operate one of the registering mechanisms, an independent mechanism for locking each registering mechanism after the first from registering movement, and adapted to be unlocked by rotation of the appropriate wheel, a transferring mechanism between each adjacent pair of registering mechanisms, each 20 adapted to act singly to transfer a count from one registering mechanism to an adjacent registering mechanism and to act conjointly to transfer the sum from a plurality 25 of registering mechanisms to the highest 30 denomination register and mechanisms adapted to act singly to unlock the locking mechanism of a higher denomination registering mechanism when a count is transferred thereto and to coact to unlock the 35 locking mechanisms from all the registering mechanisms when the sum from a plurality of registering mechanisms is transferred to the highest.
33. In a device of the class described concentric independently rotatable shafts, a registering mechanism at each end of each shaft, that at one end of each shaft adapted 40 to indicate the amount registered and means for actuating each registering mechanism at 45 the opposite end of each shaft.
34. In a device of the class described concentric independently rotatable shafts, an independent registering mechanism on each, and adjacent registering mechanisms acting 50 oppositely and a total adding device connected with the highest denomination register.
35. In a device of the class described concentric independently rotatable shafts, an independent registering mechanism on each, adjacent registering mechanisms acting oppositely, a total adding device connected with the highest denomination register and means for setting the total register to zero.
36. In a device of the class described rotatable registering mechanisms, independent rotatable elements, one appropriated to each registering mechanism and adapted to actuate the same, oscillating mechanism for actuating each registering mechanism except the 55 lowest denomination registering mechanism, and means locking each registering mechanism except the lowest denomination from advance movement.
37. A registering mechanism comprising 70 rotary registering elements, rotary elements for actuating the same for registering, a pivoted mechanism for actuating each registering element except the lowest denomination registering element, and means for 75 transferring a count directly from the lowest denomination register to the highest registering element.
38. A registering mechanism comprising 80 rotary registering elements, rotary elements 80 for actuating the same for registering, a pivoted mechanism for actuating each registering element after the lowest denomination registering element, a locking mechanism for locking each registering element 85 from registering movement, except the lowest denomination registering element and adapted to be adjusted out of operative position by the respective rotary actuating element and mechanism for adjusting the locking mechanism out of operative position for the pivotal mechanism to operate the registers.
39. A registering mechanism embracing 90 rotatable registers, rotatable means for registering directly thereto and means independent of said rotatable means for independently registering from a lower to a higher denomination register and for registering from a combination of lower registers to a higher register.
40. A registering mechanism embracing 95 rotatable registers, rotatable means for registering directly thereto, means independent of said rotatable means for registering from 100 a lower to a higher denomination register, means for locking each register from reverse movement and means for locking each register after the first from registering movement.
41. A registering mechanism embracing 110 rotatable registers, independently rotatable elements for actuating the same, part of said elements actuating the registers on their forward rotation and the remainder of the 115 rotatable elements actuating the registers on their reverse rotation, and pivotal mechanisms adapted also to actuate the rotatable registers except the lowest denomination register.
42. A registering mechanism embracing 120 rotatable oppositely acting registers, oscillating mechanism for transferring a count from one register to another, and rotary crown wheels for actuating the registers.
43. In a device of the class described register wheels appropriated to money denominations and a transferring mechanism adapted to transfer a count from one register to another comprising an oscillating 125 130

member, a reciprocating member actuated by the oscillating member, a rotatable member secured to the wheel to which the count is transferred adapted to be engaged and rotated by the reciprocating member, a member for locking the register to which the count is transferred from rotation in its registering direction and means rotatable with the register from which the count is transferred for releasing the lock prior to each transfer.

44. In a device of the class described concentric shafts, a registering wheel on each and alternate registers rotatable oppositely, a single shaft extending parallel to the concentric shafts and a plurality of rotatable elements loose on said single shaft adapted to rotate the registers in the proper direction.

45. In a device of the class described register wheels appropriated to money denominations and a transferring mechanism adapted to transfer a count from one register to another comprising an oscillating member, a reciprocating member actuated by the oscillating member, a rotatable member secured to the wheel to which the count is transferred adapted to be engaged and rotated by the reciprocating member, a member continuously rotatable with the register from which the count is transferred for actuating the oscillating mechanism, and oscillating locking member for locking the register wheels to which a count is transferred from registering movement and a rotatable member for oscillating the same to release the register wheel prior to a transfer of a count.

46. In a device of the class described concentric shafts, a register on each shaft rotatable oppositely from the adjacent lower or higher registers and independent actuating mechanisms adapted to rotate simultaneously to actuate the registers oppositely in registering.

47. In a device of the class described register wheels appropriated to money denominations, teeth pivotally secured thereto, a shaft, rotatable elements thereon adapted to mesh with the teeth on the register wheels and rotate the alternate register wheels oppositely in registering, and a transferring mechanism adapted to transfer a count from one register to another comprising an oscillating member, a reciprocating member actuated by the oscillating member, a rotatable member secured to the wheel to which the count is transferred adapted to be engaged and rotated by the reciprocating member, a member continuously rotatable with the register from which the count is transferred for actuating the oscillating mechanism, and means for automatically returning the oscillating and reciprocating member to normal after each transfer.

48. In a register a mechanism for trans-

ferring a count comprising reciprocating means for actuating the register to which the count is transferred, rotatable means controlled by the register from which the count is transferred for actuating the reciprocating means, means for locking the register to which the count is transferred from registering movement and means controlled by operation of the register from which the count is transferred for releasing the lock before each transfer.

49. In a device of the class described oppositely rotatable concentric shafts, a registering mechanism on each and mechanism for transferring a combined count from a plurality of registering mechanisms to a single registering mechanism.

50. In a registering device concentric shafts, registers thereon, a shaft extending parallel with the concentric shafts and rotatable members thereon, one opposite each register adapted to actuate alternate registers oppositely.

51. In a registering device a plurality of registering wheels, sector shaped teeth pivoted at approximately their center to each wheel having one free end projecting outwardly beyond the periphery of the wheel and the other free end projecting inwardly toward the axis of the wheel and stops secured to the wheel to engage the inwardly directed ends of the teeth and prevent the teeth from yielding in one direction.

52. In a device of the class described a dollar registering mechanism, a plurality of registering mechanisms for coins of smaller denominations, means for transferring a count to the dollar registering mechanism from one of the registering mechanisms for smaller coins or from all the registering mechanisms for small coin acting conjointly, means for locking each registering mechanism except that of the coin of lowest denomination from registering movement, and mechanism for releasing the respective locking means prior to a direct register or to a transfer from a lower register.

53. In a register of the class described a transferring mechanism comprising a member pivoted to swing, a reciprocating member pivoted thereto, an actuating member pivoted to the reciprocating member, a guide for the reciprocating member, means for actuating the swinging member, means connected with the register to which the count is transferred adapted to be actuated by said actuating member, a lock for the register to which the count is transferred, a member connected therewith and means movable simultaneously with the actuating means for engaging said member and actuating the same to release the lock.

54. In a registering device a rotatable registering mechanism, a governor for controlling the rate of rotation thereof, means

for actuating the registering mechanism, oscillating locking means for the registering mechanism and means adapted to successively oscillate said means to release the 5 registering mechanism.

55. In a device of the class described rotatable registers for coin of different denominations and alternate registers rotating oppositely and means for transferring a count 10 from a plurality of the oppositely rotatable registers to a register of higher denomination when the aggregate amount of the lower denomination registers equals a count for the highest denomination register.
56. In a device of the class described a 15 penny and a dime register, means for directly actuating each for registering independently thereto, and a transferring mechanism comprising a toothed wheel connected with the dime register, a reciprocating member for actuating the wheel in one direction, a swinging lever connected to reciprocate said member, means rotatable with the penny register adapted to actuate the lever 20 at the proper time to transfer a count to the dime register, an oscillating locking member for the dime register and means rotatable with the penny register to oscillate and release the locking member prior to the 25 transfer of the count.

57. In a device of the class described concentric shafts, a penny register on one shaft rotatable only in one direction, a dime register on another of the concentric shafts rotatable only in a direction opposite from the penny register, a dollar register on the other of said concentric shafts rotatable only in a direction opposite from the dime register, and a plurality of wheels mounted opposite 40 the registers and adapted to rotate independently or simultaneously to rotate the registers.

58. In a device of the class described registering mechanisms for dollars and 45 money of lower denomination, simultaneously rotatable actuating mechanisms for the dollar registering mechanism and lower denomination registering mechanisms and mechanism for transferring a count from 50 the lower denomination registers to the dollar registers when the rotatable actuating mechanism for the dollar register is reversely rotating from its registering rotation.

59. In a device of the class described a 55 penny and a dime register, means for directly actuating each for registering independently thereto, a transferring mechanism comprising a toothed wheel connected with the dime 60 register, a reciprocating member for actuating the wheel in one direction, a swinging lever connected to reciprocate said member, means rotatable with the penny register adapted to actuate the lever at the proper 65 time to transfer a count to the dime register,

a lock for the dime register, an oscillating member adapted to elevate the lock and means rotatable with the penny register for oscillating said member to release the lock.

60. In a device of the class described concentric shafts, a ratchet secured on the end of each shaft, a wheel secured on each shaft adjacent the ratchet wheel thereon and oppositely rotatable registering wheels on the opposite ends of the inner shafts from the ratchet wheels, each having numbers on the periphery thereof increasing in value oppositely around the periphery of the wheels.

61. In a device of the class described registering mechanisms, a mechanism for registering a count directly to each registering mechanism, mechanism for transferring a count from a lower to a higher denomination register and operable only to transfer the count to the higher denomination register after the direct registering mechanism has transferred the direct count to said higher denomination register, independent means for locking each registering mechanism except the first from registering movement and mechanism for releasing the respective locking means prior to a direct register or a transfer from a lower register.

62. In a device of the class described a penny and a dime register, means for directly actuating each for registering independently thereto, a transferring mechanism comprising a toothed wheel connected with the dime register, a reciprocating member for actuating the wheel in one direction, a swinging lever connected to reciprocate said member, means rotatable with the penny register adapted to actuate the lever at the proper time to transfer a count to the dime register, a lock for the dime register, an oscillating member adapted to elevate the lock, means rotatable with the penny register for oscillating said member to release the lock, and independent means for automatically returning the lock and oscillating member to normal position and the mechanism for actuating the register.

63. In a device of the class described concentric shafts, a register rigidly secured on each shaft, each appropriated to a different money denomination, a transferring mechanism adapted to rotate one of the concentric shafts oppositely from the other to transfer a count from one register to the other, a locking mechanism for each register, means releasing the same prior to each transfer and means for automatically returning the locking mechanism to locking position.

64. In a device of the class described concentric shafts, a register rigidly secured on each shaft, each appropriated to a different money denomination, a transferring mechanism adapted to rotate one of the concentric shafts oppositely from the other to transfer a count from one register to the other, a

rotatable member adapted to directly actuate each register and actuating one register oppositely from the other.

65. In a device of the class described rotatable independent registering mechanisms, rotatable mechanisms, each adapted when rotating in one direction to actuate the appropriate registering mechanism and transferring mechanism for transferring a count from a lower to a higher denomination register and adapted to operate only when the rotatable actuating mechanism for the register to which the count is transferred is rotating oppositely from its direction for actuating the registering mechanism.

66. In a device of the class described a penny register, a dime register having its axis concentric with the axis of the penny register, a mechanism adapted to actuate the dime register oppositely from the penny register to transfer a count to the dime register and a guide for said transferring mechanism.

67. In a registering device a plurality of registering wheels, teeth pivoted to each wheel having a portion projecting outwardly beyond the periphery of the wheel and a portion projecting inwardly toward the axis of the wheel, stops secured to the wheel to engage the inwardly directed portions of the teeth and prevent the teeth from yielding in one direction, and a spring for each tooth for normally holding the same to project beyond the periphery of the wheel.

68. In a device of the class described registers, an independent rotatable actuating means for each register, alternate registers operated on the opposite rotation of the actuating means and transferring mechanisms, each operating to transfer a count to the appropriate register only when the rotatable actuating means for that register is rotating oppositely from its registering direction.

69. In a device of the class described a penny register, a dime register, a mechanism adapted to actuate the dime register oppositely from the penny register to transfer a count to the dime register, a guide for said transferring mechanism, means for locking the dime and penny register from movement reversely to their registering movement and a releasable lock for locking the dime register from registering movement.

70. In a device of the class described a plurality of registers adapted to rotate in the same direction, an intermediate register adapted to rotate oppositely therefrom when registering, means for locking each register after the first from registering movement, and rotatable means for actuating each register and releasing the locking means prior to actuating the register.

71. In a device of the class described concentric dime and penny shafts, a dime reg-

ister on one shaft, a penny register on the other shaft, a ratchet wheel on the dime shaft, a pivoted mechanism adapted to actuate said ratchet to advance the dime register to make a count and an arm rotatable with the penny shaft adapted to actuate the pivoted mechanism when the penny register completes each revolution.

72. In a cash register rotatable registering wheels for dollars, dimes and pennies, means for independently actuating the wheels in registering, a member rotatable with the dime registering wheel, mechanism adjusted thereby prior to the dime wheel making each complete revolution and means rotatable with the independent actuating means for the dime register adapted to actuate said adjusted mechanism to impart a partial rotation to the dollar register wheel.

73. In a device of the class described a plurality of registering mechanisms, a centrifugal governor for controlling the speed thereof when registering, an independent rotatable mechanism for actuating each registering mechanism and an oscillating transferring mechanism between each pair of registers operating oppositely in transferring a count.

74. In a device of the class described a plurality of registering wheels for dollars, dimes and pennies, teeth on the penny wheel adapted to yield in one direction, teeth on the dime wheel adapted to yield in a direction opposite thereto, teeth on the dollar register adapted to yield in a direction opposite to the teeth on the dime wheel and rotatable elements adapted when rotating in one direction to engage the teeth on the respective register to actuate the register and when rotating oppositely to pass the teeth without actuating the register.

75. In a cash register rotatable registering wheels for dollars, dimes and pennies, means for independently actuating the wheels in registering, a member rotatable with the dime registering wheel, means adjusted thereby prior to the dime wheel making each complete revolution, means rotatable with the independent actuating means for the dime register adapted to actuate said adjusted mechanism to impart a partial rotation to the dollar register wheel, and means for automatically moving the adjusted mechanism to normal position to be engaged by the rotatable member prior to the dime wheel completing the next rotation.

76. In a device of the class described concentric dime and penny shafts, a dime register on one shaft, a penny register on the other shaft, a ratchet wheel on the dime shaft, a pivoted mechanism adapted to actuate said ratchet to advance the dime register to make a count, an arm rotatable with the penny shaft adapted to actuate the pivoted mechanism when the penny register

completes each revolution, a member for locking the dime register from registering movement, means connected therewith for actuating the same to release the dime register and a member rotatable with the penny shaft for actuating the same once for each rotation of the penny register.

77. In a device of the class described concentric dime and penny shafts, a dime register on one shaft, a penny register on the other shaft, a ratchet wheel on the dime shaft, a pivoted mechanism adapted to actuate said ratchet to advance the dime register to make a count, an arm rotatable with the penny shaft adapted to actuate the pivoted mechanism when the penny register completes each revolution, a member for locking the dime register from registering movement, means connected therewith for actuating the same to release the dime register, a member rotatable with the penny shaft for actuating the same once for each rotation of the penny register, means secured to the locking member adapted to yield in one direction, and nonyieldable in the opposite direction for releasing the lock and a rotatable actuating mechanism for registering to the dime register adapted to release the lock before registering each count.

78. In a device of the class described registering mechanisms for dollars, dimes and pennies, means for actuating each registering mechanism, a member rotatable with the dime registering mechanism, a transferring mechanism adapted to be adjusted thereby into position to be actuated to transfer a count to the dollar register, coacting spring members for engaging and yieldingly supporting the transferring mechanism in adjusted position, means for actuating the transferring mechanism to register on the dollar registering mechanism, and means for adjusting the transferring mechanism to normal as the same is operated to transfer the count and thereby release the same from the yielding support.

79. In a device of the class described oppositely rotatable registering mechanisms, actuating mechanisms for the same rotatable in the same direction, and a governor connected to control the rate of rotation of all the actuating mechanisms.

80. In a device of the class described registers for dollars, dimes and pennies, an independent mechanism for operating each register, a transferring mechanism normally out of operative position, a member adapted to adjust the same into operative position as the amount on the dime register equals a count on the dollar register, pivotally supported members depending to engage and support the transferring mechanism in adjusted position, a rotatable member adapted to actuate the transferring mechanism,

means for adjusting the transferring mechanism to normal after the transfer and pivoted lever engaging beneath a part of the transferring mechanism for supporting the same in normal position.

81. In a device of the class described registers, means for transferring a count from one register to the other, means for locking one register from registering movement, a shaft, means secured to one end thereof adapted to engage and release the locking means, a member secured to said shaft, means for actuating said member to operate the shaft, and means for registering directly to the dime register adapted to release the lock independently of the aforesaid releasing means.

82. In a device of the class described registers appropriated to dollars, dimes and pennies, a rotatable mechanism for actuating each register, transferring mechanisms, one for transferring a count to the dime register and the other for transferring a count to the dollar register and mechanisms controlled by operation of the penny register adapted to operate both the dime transferring mechanism and the dollar transferring mechanism.

83. In a device of the class described a plurality of registers, a mechanism for actuating alternate registers oppositely to prevent several counts from being registered as one thereon, a transferring mechanism adapted to transfer a count from one register to another and means for locking one of the registers from registering movement adapted to be actuated by either the actuating or transferring mechanism.

84. In a registering device rotatable registering elements, adjacent registering elements rotative oppositely to prevent a plurality of counts being registered as one thereon, rotatable actuating elements and a rotatable governor controlling the rate of operation of all of said elements.

85. In a device of the class described concentric shafts, a register on each shaft and alternate registers rotatable oppositely, a transferring mechanism normally out of operative position, means rotatable with one of the registers for shifting the transferring mechanism into operation position, coacting members for holding the transferring mechanism in operative position and means for actuating the transferring mechanism when in said shifted position.

86. In a device of the class described a rotatable registering wheel, a lock adapted to hold the same from registering movement, means pivoted to the lock adapted to yield in one direction and a wheel adapted to successively engage said means to successively release the lock from the registering wheel when rotating in one direction and when rotating oppositely adapted to actuate the

yielding pivoted means without actuating the lock.

87. In a device of the class described a dollar, a dime and a penny register, a transferring mechanism for transferring a count from the penny register to the dime register, a transferring mechanism for transferring a count from the dime register to the dollar register, mechanism for actuating the penny register and also adapted to actuate the mechanism for transferring a count from the dime to the dollar register, means for locking the dollar register from registering movement and means operating with the transferring mechanism to shift the locking mechanism out of engagement prior to the transfer.

88. In a device of the class described concentric shafts, a register on each shaft, a transferring mechanism normally out of operative position, means rotatable with one of the registers for shifting the transferring mechanism into operative position, means for actuating the transferring mechanism when in said shifted position, a cam lever carried by the transferring mechanism, and a friction roller for engaging the cam lever and releasing the transferring mechanism from said actuating mechanism as the transferring mechanism is being operated.

89. In a device of the class described a dollar, a dime and a penny register, means for actuating each, a transferring mechanism between the penny and dime registers, a transferring mechanism between the dime and dollar registers, means rotatable with the dime register for shifting the last named transferring mechanism into position to be operated, means for yieldingly holding the same in said position until actuated and means movable with the actuating means for the dime shaft for actuating the dollar transferring mechanism.

90. In a registering device a register wheel, a plurality of axial studs secured to the side of the wheel, teeth journaled on the studs, stops preventing the teeth yielding in one direction and a torsion spring for normally holding the teeth to project beyond the periphery of the wheel.

91. In a device of the class described dollar, dime and penny registers, transferring mechanisms, one actuated by rotation of the penny register in one direction to transfer a count to the dime register from the penny register and the other transferring mechanism actuated by reverse rotation of the dime register to transfer a count to the dollar register, and means for actuating the last named or dollar transferring mechanism to transfer a combined count from the penny and dime registers to the dollar register.

92. In a device of the class described a dollar, a dime and a penny register, means for actuating each, a transferring mechanism

between the penny and dime registers, a transferring mechanism between the dime and dollar registers, means rotatable with the dime register for shifting the last named transferring mechanism into position to be operated, means for yieldingly holding the same in said position until actuated, means movable with the actuating means for the dime shaft for actuating the dollar transferring mechanism, and means rotatable with the means for actuating the penny register adapted to actuate the dollar transferring mechanism when the sum registered on the dime and penny registers equals a dollar.

93. In a registering device rotatable registering elements, rotatable actuating elements, a rotatable governor controlling the rate of operation of all of said elements, a transferring mechanism for transferring a count from each lower to the adjacent higher registering element, rotatable means for actuating each transferring mechanism, a locking device for each registering mechanism after the first and means for releasing each locking device prior to each transfer of a count to its register.

94. In a device of the class described a dollar, a dime and a penny registering mechanism, and transferring mechanisms, one operated by the penny registering mechanism to transfer a count to the dime register from the penny register and the other transferring mechanism adapted to be operated either by the dime registering mechanism to transfer a count to the dollar register or by the penny registering mechanism to transfer a count to the dollar register.

95. In a device of the class described a dollar, a dime and a penny register, means for actuating each, a transferring mechanism between the penny and dime registers, a transferring mechanism between the dime and dollar register, means rotatable with the dime register for shifting the last named transferring mechanism into position to be operated, means for yieldingly holding the same in said position until actuated, means movable with the actuating means for the dime shaft for actuating the dollar transferring mechanism, means rotatable with the means for actuating the penny register adapted to actuate the dollar transferring mechanism when the sum registered on the dime and penny registers equals a dollar, means for releasing the dollar transferring mechanism from either actuating mechanism and means for automatically returning the transferring mechanism into position to again be shifted into operative position.

96. In a device of the class described a rotatable registering wheel, a lock adapted to hold the same from registering movement, means pivoted to the lock adapted to yield in one direction, a wheel adapted to suc-

sively engage said means to successively release the lock from the registering wheel when rotating in one direction and when rotating oppositely adapted to actuate the 5 yielding pivoted means without actuating the lock and means for returning the lock to normal after each actuation thereof.

97. In a device of the class described registering mechanisms appropriated to dollars, 10 dimes and pennies, rotatable means for actuating the same, a transferring mechanism adapted to be oscillated into position to be actuated to transfer a count and means for oscillating the transferring mechanism when 15 in this position to transfer a count from a lower to a higher denomination register.

98. In a device of the class described concentric shafts, a ratchet secured on one end of each shaft, a register wheel secured on 20 each shaft adjacent the ratchet wheel thereon, registering wheels on the opposite ends of the inner shafts from the ratchet wheels, each having numbers on the periphery thereof, a gear secured to the outer shaft and a 25 total adding register driven by said gear.

99. In a registering device rotatable registering elements, rotatable actuating elements, a rotatable governor controlling the rate of operation of all of said elements, 30 actuating mechanisms for rotating alternate registers oppositely and transferring mechanisms operating oppositely in transferring a count.

100. In a device of the class described a 35 register, an oscillating locking member adapted to lock the same from registering movement, a projection on the locking member and a rotating wheel adapted to successively advance the register and also to 40 engage the projection and successively release the locking member from the register.

101. In a device of the class described oppositely rotatable registers appropriated to different money denominations, transferring 45 mechanisms, one between each pair of registers and alternate vertical depending oscillatable transferring mechanisms operating oppositely in transferring the count to the respective registers.

50 102. In a registering device a register wheel, a plurality of axial studs secured to the side of the wheel, teeth journaled on the studs, stops preventing the teeth yielding in one direction, a torsion spring on each stud 55 for normally holding the teeth to project beyond the periphery of the wheel, rotatable means for actuating the register wheel adapted to engage the teeth when rotating in one direction and automatically actuating 60 the teeth when rotating reversely to permit the same to pass without actuating the register.

103. In a device of the class described oppositely rotatable registering wheels, independent means for permanently locking 65

each from rotation reversely to their registering movement, and independent means for locking each registering wheel after the first from rotation in the direction of registering.

104. In a device of the class described the combination of a plurality of registers and a plurality of actuating members, and pivoted and rigid teeth secured to the registers and actuating members a spring engaged to 70 each tooth adapted to project the same normally outward, said pivoted and rigid teeth normally out of mesh but adapted to intermesh when the actuating members are rotated.

105. In a device of the class described concentric shafts, a registering wheel secured on each, means for preventing each shaft rotating in one direction, dime and penny register wheels on two of the shafts 75 having their peripheries numbered reversely, a total register connected with the other shaft adapted to register dollars only, mechanisms for transferring a count from the appropriate lower to the appropriate higher 80 denomination register, each adapted to operate only when the adjacent lower or adjacent higher transferring mechanism is at rest, and independent releasable means for locking each register to which a count may 85 be transferred from registering movement.

106. In a registering device mechanism for transferring a count embracing shafts, means connecting the same to rotate together, a lever on one end of one shaft, a 100 normally elevated pawl on the same shaft, means for engaging the lever to lower the pawl, means for engaging the pawl when lowered to swing the shaft and lever, means secured to the shaft for actuating a register 105 one count, and means for holding the pawl in lowered position independent of the means for lowering the same until the pawl is engaged to actuate the transferring mechanism.

107. In a device of the class described oppositely rotatable concentric shafts registering mechanisms thereon appropriated to different denominations of money, each registering mechanism operable oppositely 110 from the adjacent lower registering mechanism and a governor for regulating the rate of movement of the oppositely operating registers.

108. In a device of the class described 120 concentric shafts, a registering wheel secured on each, means for preventing each shaft rotating in one direction, dime and penny register wheels on two of the shafts having their peripheries numbered reversely, a total register connected with the other shaft adapted to register dollars only, mechanisms for transferring a count from the appropriate lower to the appropriate 125 higher denomination register, each adapted 130

- to operate only when the adjacent lower or adjacent higher transferring mechanism is at rest, independent releasable means for locking each register to which a count may 5 be transferred from registering movement, and a mechanism operated by each transferring mechanism for adjusting the respective locking mechanism to permit actuation of the appropriate register.
109. In a registering device mechanism for transferring a count embracing shafts, means connecting the same to rotate together, a lever on one end of one shaft, a normally elevated pawl on the same shaft, 15 means for engaging the lever to lower the pawl, means for engaging the pawl when lowered to swing the shaft and lever, means secured to the shaft for actuating a register one count, means for holding the pawl in 20 lowered position independent of the means for lowering the same until the pawl is engaged to actuate the transferring mechanism, a roller and said lever having a cam surface to engage the roller thereby elevating the pawl after the transfer.
110. In a device of the class described a registering wheel, teeth pivoted thereto adapted to yield in one direction, a locking member for the register, means pivoted 30 thereto adapted to yield in the same direction as the teeth and means for advancing the registering wheel adapted to engage said means prior to engaging the teeth and thereby release the locking member and actuate the registering wheel directly after the release.
111. In a device of the class described registers appropriated to different money denominations, mechanisms for transferring a 40 count from the appropriate lower to the appropriate higher denomination register, each adapted to operate only when the adjacent lower or adjacent higher transferring mechanism is at rest, independent releasable means 45 for locking each register to which a count may be transferred from registering movement, a mechanism operated by each transferring mechanism for adjusting the respective locking mechanism to permit actuation of the appropriate register, and means for quickly and automatically returning each locking mechanism to locking position after each actuation of its register.
112. In a registering device mechanism 55 for transferring a count embracing shafts, means connecting the same to rotate together, a lever on one end of one shaft, a normally elevated pawl on the same shaft, means for engaging the lever to lower the 60 pawl, means for engaging the pawl when lowered to swing the shaft and lever, means secured to the shaft for actuating a register one count, means for holding the pawl in lowered position independent of the 65 means for lowering the same until the pawl
- is engaged to actuate the transferring mechanism, a roller, said lever having a cam surface to engage the roller thereby elevating the pawl after the transfer, a lock for securing the register to which the count is transferred from advance movement and mechanism secured to and operated by one of said shafts for releasing the lock prior to the transfer.
113. In a device of the class described concentric shafts, a registering wheel secured on each, means for preventing each shaft rotating in one direction, dime and penny register wheels on two of the shafts having their peripheries numbered reversely 80 and a total register connected with the other shaft adapted to register dollars only.
114. In a device of the class described registers appropriated to different denominations of money and an oscillating transferring mechanism for each register after the first and each transferring mechanism adapted to oscillate oppositely from the adjacent lower or higher transferring mechanism in transferring each count.
115. In a registering device of the class described a transferring mechanism comprising a swinging shaft, a normally elevated member on said shaft, a cam lever connected with said normally elevated member, 95 a rotating arm for engaging the cam lever and rotating the shaft to lower said member prior to the transfer, mechanism for engaging said lowered member and swinging the shaft and means secured to the swinging 100 shaft adapted to actuate a register to transfer a count thereto and a roller engaging the cam lever to elevate the member.
116. In a device of the class described concentric shafts, registers thereon, an actuating mechanism for each shaft comprising a 105 shaft, wheels journaled thereon and a gear secured to each wheel.
117. In a device of the class described registers, each appropriated to a different denomination of money, and vertical depending oscillating transferring mechanisms, one for transferring a count from each lower to the next higher denomination register and said transferring mechanisms adapted only 115 to oscillate oppositely in transferring each count.
118. In a registering device of the class described a transferring mechanism comprising a swinging shaft, a normally elevated member on said shaft, mechanism for rotating the shaft to lower said member prior to the transfer, mechanism for engaging said lowered member, and swinging the shaft, means secured to the swinging shaft 120 adapted to actuate a register to transfer a count thereto, a shaft connected with the swinging shaft and rotated by swinging thereof, a releasing mechanism actuated by rotation of the shaft and a locking member 125
- 130

- normally locking the register from movement and actuated by the releasing mechanism.
119. In a device of the class described registers each appropriated to a different denomination of money, and oscillating transferring mechanisms, one for transferring a count from each lower to the next higher denomination register, said transferring mechanisms adapted only to oscillate oppositely in transferring each count, and independently rotatable means for actuating each oscillating transferring mechanism to transfer a count at the proper time. 70
120. In a device of the class described a dollar, a dime and a penny register, a wheel for actuating each register, a transferring mechanism for transferring a count from the dime to the dollar register, means rotatable with the dime register for adjusting the transferring mechanism into position to be actuated to transfer a count when the dime register has completed each rotation, and means rotatable with the actuating wheel for the dime register adapted to actuate the transferring mechanism. 75
121. In a device of the class described registering mechanisms appropriated to different denominations of money, each registering mechanism operable oppositely from the adjacent lower registering mechanism, a governor for regulating the rate of movement of the oppositely operating registers, and actuating mechanisms for the registering mechanisms directly controlled by the governor. 80
122. In a device of the class described registers, each appropriated to a different denomination of money, oscillating transferring mechanisms, one for transferring a count from each lower to the next higher denomination register, said transferring mechanisms adapted to transfer a count only when oscillating oppositely, independently rotatable means for actuating each register and a mechanism rotatable with each register to oscillate the transferring mechanism for the next higher register. 85
123. In a device of the class described a dollar, a dime and a penny register, a rotatable wheel for actuating each register, a transferring mechanism for transferring a count from the dime to the dollar register, means rotatable with the dime register for adjusting the transferring mechanism into position to be actuated to transfer a count when the dime register has completed each rotation, means rotatable with the actuating wheel for the dime register adapted to actuate the transferring mechanism, and means rotatable with the actuating wheel for the penny register adapted to actuate the transferring mechanism when the total sum registered on the penny and dime registers equals a dollar. 90
124. In a device of the class described registers, each appropriated to a different denomination of money, oscillating transferring mechanisms, one for transferring a count from each lower to the next higher denomination register, said transferring mechanisms adapted to transfer each count only when oscillating oppositely, independently rotatable means for actuating each register, a mechanism rotatable with each register to oscillate the transferring mechanism for the next higher register, and rotatable means independent from all of the aforesaid rotatable mechanisms adapted to oscillate a transferring mechanism to transfer a combination count to a register from a plurality of registers of lower denominations than the register to which the count is transferred. 95
125. In a device of the class described a dollar, a dime and a penny register, a rotatable wheel for actuating each register, a transferring mechanism for transferring a count from the dime to the dollar register, means rotatable with the dime register for adjusting the transferring mechanism in position to be actuated to transfer a count when the dime register has completed each rotation, means rotatable with the actuating wheel for the dime register adapted to actuate the transferring mechanism, means rotatable with the actuating wheel for the penny register adapted to actuate the transferring mechanism when the total sum registered on the penny and dime registers equals a dollar, and means for holding the transferring mechanism in its adjusted position until either of the rotatable means has actuated the same to transfer the count to the dollar register. 100
126. In a device of the class described register wheels, a plurality of teeth pivoted to the side of each projecting outwardly beyond the periphery thereof and yieldable in one direction relatively of the wheel and springs holding the teeth projected beyond the periphery of the wheels. 105
127. In a device of the class described rotatable actuating elements, rotatable registering elements, spring controlled radially directed teeth pivoted to part of the elements and axially directed teeth rigidly secured to the other elements to mesh therewith. 110
128. In a device of the class described oppositely rotatable registers, each appropriated to a money denomination, a mechanism for independently actuating each register, and vertical depending oscillating transferring mechanisms, one mechanism for transferring a count from each lower to the next higher denomination register. 115
129. In a device of the class described a dollar register, a dime register and a penny register, a swinging shaft, a pawl on each end thereof, independent actuating means 120
- 130

for each register, independent means actuated by the actuating means for the dime and penny register, each for engaging one of the pawls to swing the shaft and a pawl 5 on the shaft adapted to actuate the dollar register to transfer a count thereto.

130. In a device of the class described registers, each appropriated to a money denomination, a mechanism for independently actuating 10 each register, vertical, depending oscillating transferring mechanisms, one mechanism for transferring a count from each lower to the next higher denomination register, oscillating means for locking each register to which 15 a count may be transferred from registering movement and mechanism operated by the respective oscillating transferring mechanism to release the locking means prior to transferring a count.

131. In a device of the class described a dollar register, a dime register and a penny register, a swinging shaft, a pawl on each end thereof, independent actuating means for each register, independent means actuated by the actuating means for the dime and penny register, each for engaging one of the pawls to swing the shaft, a pawl on the shaft adapted to actuate the dollar register to transfer a count thereto, a shaft connected with and rotated by said swinging shaft, a lock for the dollar register and a connection between the rotatable shaft and lock for releasing the same.

132. In a device of the class described registers, each appropriated to an money denomination, a mechanism for independently actuating each register, vertical depending oscillating transferring mechanisms, one mechanism for transferring a count from 35 each lower to the next higher denomination register, oscillating means for locking each register to which a count may be transferred from registering movement, mechanism operated by the respective oscillating transferring mechanism to release the locking means prior to transferring a count, and means for immediately returning each locking means to locking position after each transfer of each count.

133. In a device of the class described a plurality of register wheels having toothed peripheries, teeth pivoted to the register wheels, the teeth pivoted reversely on alternate wheels and adapted to rotate alternate 55 wheels reversely.

134. In a device of the class described registers, each appropriated to a money denomination, a mechanism for independently actuating each register, vertical depending oscillating transferring mechanisms, one mechanism for transferring a count from each lower to the next higher denomination register, and rotatable mechanisms for actuating each transferring mechanism and adapted 60 to oscillate each transferring mecha-

nism alternately from the operation of the mechanism for independently operating the register to which the count is transferred.

135. In a device of the class described registering mechanisms appropriated to different denominations of money, each registering mechanism operable oppositely from the adjacent lower registering mechanism, a governor for regulating the rate of movement of the oppositely operating registers, 70 actuating mechanisms for the registering mechanisms directly controlled by the governor, transferring mechanisms, one between each pair of registering mechanisms and a rotatable actuating mechanism for each 75 transferring mechanism controlled by the governor.

136. In a device of the class described register wheels for different money denominations, actuating wheels for the register 85 wheels, cams rotatable with a plurality of the actuating wheels, a transferring mechanism adapted to be actuated by any cam to transfer a count from one or a plurality of counters acting singly or in combination 90 to another counter, a lock for each register to which a count may be transferred normally locking the register from advance movement and means operated by the cams for releasing the locks prior to transferring 95 a count.

137. In a device of the class described register wheels, a plurality of teeth pivoted to the side of each, projecting outwardly beyond the periphery thereof and yieldable in one direction relatively of the wheel, and a 100 spring adapted to hold the teeth in normal position and return the same to normal position after each tooth has yielded inwardly.

138. In a device of the class described registers, a mechanism for directly registering to each register, a transferring mechanism for transferring a count from each lower to the next higher register and inoperative when the direct registering mechanism is registering to the same register that it is adapted to transfer to, non-releasable means for locking all of the registers from movement reverse to the registering movement, and releasable means for locking the registers from registering movement except the first register.

139. In a device of the class described a registering element, an actuating element, axially directed teeth secured to one of the 120 elements, radially directed teeth secured to the other element, and the teeth secured to one of the elements being pivoted.

140. In a device of the class described registers, a mechanism for directly registering 125 to each register, a transferring mechanism for transferring a count from each lower to the next higher register and inoperative when the direct registering mechanisms is registering to the same register that it is 130

- adapted to transfer to, non-releasable means for locking all of the registers from movement reverse to the registering movement, releasable means for locking the registers 5 from registering movement except the first register, means for releasing the means locking the registers from registering movement, and means for returning the locking means to normal after the registering operation. 141. In a device of the class described a dollar, a dime and a penny register wheel, teeth pivoted on said register wheels and the teeth on alternate wheels reversed adapting 15 the alternate registers operating oppositely and independent means for engaging the teeth of each wheel and actuating the registers. 142. In a device of the class described a 20 registering element, an actuating element, axially directed teeth secured to one of the elements, radially directed teeth secured to the other element, the teeth secured to one of the elements being pivoted, and springs 25 secured to the pivoted teeth for holding the same extended. 143. In a device of the class described a plurality of register wheels, teeth pivoted to each wheel, the teeth on alternate wheels 30 pivoted to yield oppositely and means for engaging the teeth and actuating the registers. 144. In a registering device a plurality of registers, a transferring mechanism operating 35 to transfer a count from one register to another, independent actuating mechanisms for each register, each adapted to actuate the transferring mechanism except the actuating mechanism for the register to 40 which the count is transferred, means adapted to return the transferring mechanism to normal after each actuation, a lock for the register to which the count is transferred, means for releasing the lock and means for 45 returning the lock to normal after each actuation of the register. 145. In a device of the class described register wheels, radially directed teeth pivoted to said wheels and a torsion spring secured 50 to each tooth adapted to permit the teeth to yield in one direction and return the same to normal after yielding. 146. In a device of the class described concentric shafts, a registering device on 55 each, a shaft, a plurality of independent freely rotatable register actuating members on said shaft and a single governor connected with each actuating mechanism adapted to control the rate of movement 60 thereof. 147. In a device of the class described a plurality of registers, a transferring mechanism adapted to transfer a count from each 65 lower to the next higher register and rotatable mechanisms for each register after the 70 first, one rotatable mechanism adapted to actuate the proper register and the other mechanism rotatable oppositely to actuate the transferring mechanism for the same register. 148. In a device of the class described, means for locking each register wheel from registering movement except the lowest denomination wheel, means for actuating the register wheels adapted to release the lock 75 before actuating the respective register and transferring mechanism for transferring a count from a lower to a higher denomination register adapted also to release the lock before each transfer. 149. In a device of the class described register wheels, teeth pivoted to the side thereof, actuating wheels, and teeth secured to the side thereof adjacent the periphery adapted to engage the pivoted teeth of the 80 registering wheels. 150. In a device of the class described concentric shafts, a registering device on each, a shaft, a plurality of independent freely rotatable register actuating members 85 on said shaft, a single governor connected with each actuating mechanism adapted to control the rate of movement thereof, a transferring mechanism for each register after the first, and means for actuating each 90 in transferring a count. 151. In a device of the class described registers for different money denominations, a plurality of mechanisms for independently actuating each register after the lowest denomination register and each mechanism operable to actuate its register only when the other mechanism is neutral, rotatable means for actuating the lowest denomination register and means rotatable therewith adapted to actuate one of the mechanisms registering to the highest denomination register for transferring a count thereto from a plurality of the lower registers acting 95 jointly. 152. In a device of the class described registers appropriated to different money denominations, a transferring mechanism, connected simultaneously rotatable members, one adapted to rotate the respective register in registering and the other member adapted to actuate the transferring mechanism for each rotation of the appropriate register, said transferring mechanism adapted to be actuated by the rotatable members 100 of different denomination registers for 105 transferring a combination count from a plurality of registers. 153. In a device of the class described oppositely rotatable registering wheels, means for locking each register wheel from registering movement except the lowest denomination wheel, means for actuating the register wheels adapted to release the lock before actuating the respective register, trans- 110 115 120 125 130

ferring mechanism for transferring a count from a lower to a higher denomination register adapted also to release the lock before each transfer, and independent means 5 for locking each register wheel from movement reversely to its direction of registering.

154. In a device of the class described 10 concentric shafts, a registering device on each, a shaft, a plurality of independent freely rotatable register actuating members on said shaft, a single governor connected with each actuating mechanism adapted to control the rate of movement thereof, a 15 transferring mechanism for each register after the first, means for actuating each in transferring a count, and means rotatable with the actuating member for the lowest denomination register adapted to actuate 20 one of the transferring mechanisms to transfer a count from a plurality of the registers to a higher register when the combined sum of the registers equals one on the higher register.

25 155. In a device of the class described a register wheel, teeth pivoted to one face of the wheel having an inwardly and an outwardly directed tail, stops secured to the face of the wheel and springs for holding 30 the inwardly directed tails of the teeth against the stops and projecting the outwardly directed tails beyond the periphery of the wheel.

156. In a device of the class described a 35 plurality of registers, a registering element marked with digits on its periphery operable with two of the registers, a total adding register operated by one of said registers and means for shifting the total register 40 out of operation.

157. In a device of the class described a toothed register wheel, a locking member for engaging the successive teeth and holding the register wheel from registering 45 movement, an oscillating mechanism connected with the locking member to release the same, a rotatable member for actuating the oscillating mechanism once for each rotation thereof to release the locking member, a member secured to the locking member 50 to yield when engaged on one side to prevent release of the locking member and adapted when engaged on the opposite side to actuate the locking member to release 55 the register wheel entirely independently of the oscillating mechanism.

158. In a device of the class described a register wheel, a locking member therefor, a pin secured to the locking member a bell 60 crank lever having one end slotted to receive the pin, a transferring mechanism, means operating in advance thereof to actuate the bell crank lever to release the lock prior to a transfer of a count to said register, a rotatable wheel for actuating the reg-

ister wheel and a pivoted member secured to the other arm of the bell crank lever adapted to be engaged by the rotatable wheel to release the locking member prior to each actuation of the register wheel by the rotatable wheel.

159. In a device of the class described a register wheel having peripheral teeth and pivotal teeth, a lock for engaging the peripheral teeth, a member engaging the lock, 70 coating members for actuating the member to release the lock, a mechanism for transferring a count to the register while the lock is released, a spring for returning the lock to engage the successive teeth, a 75 rotatable wheel for engaging the pivoted teeth and directly registering to the register and said wheel engaging the lock and releasing the same from the register prior to each count registered.

160. In a device of the class described a register wheel, a lever for holding the same from registering, a transferring mechanism, means operating therewith for actuating the lever to release the register wheel and a 90 direct registering mechanism adapted to engage and release the lever before actuating the register.

161. In a device of the class described a register wheel having peripheral teeth, a 95 ratchet wheel rigidly connected with the register wheel, a lock for the register wheel engaging the peripheral teeth thereof, a transferring mechanism comprising in part a pawl to engage and rotate the ratchet and 100 register wheel, means connected with the pawl to release the lock before the pawl actuates the ratchet and means for returning said means to normal.

162. In a device of the class described a 105 registering wheel, a lock therefor, a combined transferring and lock releasing mechanism adapted to first release the lock and then actuate the registering wheel, a direct actuating mechanism for registering to the 110 register adapted to both release the lock and actuate the register wheel independently of the transferring mechanism, and a total adding register connected with, and counting one for each actuation of the registering 115 wheel.

163. In a device of the class described a register wheel having peripheral teeth, a pivotally supported locking lever having the end on one side of the pivot pawl shaped to 120 engage the teeth, a pin secured to the lever on the opposite side of the pivot, a transferring mechanism for actuating the register wheel and means operated by the transferring mechanism for engaging the pin and 125 swinging the pawl end of the lever out of engagement with the registering mechanism.

164. In a device of the class described a register wheel having peripheral teeth, a pivotally supported locking lever having the 130

end on one side of the pivot pawl shaped to engage the teeth, a pin secured to the lever on the opposite side of the pivot, a transferring mechanism for actuating the register 5 wheel, means operated by the transferring mechanism for engaging the pin and swinging the pawl end of the lever out of engagement with the registering mechanism, a detent pivoted to the lever between the pivot 10 point and pin, and releasable in one direction, an actuating wheel for engaging the detent to release the pawl and for actuating the registering wheel when the pawl is released, and a total adding register directly 15 coupled with the registering wheel.

165. In a total adding register, register wheels, a lock for each after the first, a transfer mechanism between each pair of register wheels adapted to release the lock 20 and actuate the higher denomination register wheel, direct registering mechanisms for the register wheels adapted to engage and release the lock for the respective register wheel before actuating the same, a total 25 adding register connected with the highest denomination register, and wheels connected with the lower denomination registers, having numerals thereon to read in alinement, with the total adding register.

166. In a device of the class described concentric shafts, a penny register on one shaft, a dime register on the other shaft, a transferring mechanism comprising a ratchet wheel on the dime shaft, a pawl for actuating 30 the same, a vertical lever pivotally connected with the pawl and an arm on the penny shaft for engaging the lever thereby actuating the dime register.

167. In a device of the class described concentric shafts, a penny register on one shaft, a dime register on the other shaft rotatable oppositely from the penny register, independent mechanisms for actuating the penny and dime registers oppositely and a lock 45 adapted to prevent rotation of the dime register.

168. A registering mechanism comprising registering wheels appropriated to money denominations, the odd number of register 50 wheels rotatable in one direction and the even number of register wheels rotatable oppositely therefrom, a shaft, independent actuating mechanisms for the oppositely acting registers, all of said mechanisms mounted on said shaft and rotatable independently of each other, and oppositely acting transferring mechanisms between the registers for transferring a count from the adjacent lower to the adjacent higher register.

169. In a registering device dollar, dime and penny registers and transferring mechanisms between the registers, one acting oppositely from the other in transferring a count to its respective register, and direct 65 registering mechanisms for the registers

adapted to actuate the dime register oppositely from the dollar and penny registers.

170. In a device of the class described a dollar and a penny register rotatable in the same direction, a dime register rotatable oppositely therefrom, oppositely acting transferring mechanisms for actuating the dime and the dollar registers oppositely in transferring a count thereto, a total adding register connected with the dollar register and oppositely rotatable wheels adjacent the total adding register for indicating the sums less than a dollar. 70 75

171. In a device of the class described a plurality of standards, concentric shafts journaled thereto, oppositely rotatable registers secured to the shafts, oppositely acting transferring mechanisms journaled between the standards and mechanism for actuating the transferring mechanisms to transfer a 80 count to the proper registers.

172. In a device of the class described a plurality of standards, concentric shafts journaled thereto, oppositely rotatable registers secured to the shafts, oppositely acting 90 transferring mechanisms journaled between the standards, mechanism for actuating the transferring mechanisms to transfer a count to the proper registers, a total adding register and a plurality of wheels having numbers on the periphery, said total adding register and wheels adapted to display the total dollars and cents registered. 95

173. In a device of the class described a registering device comprising a base, parallel standards rigidly secured thereto, concentric shafts journaled in the standards, a registering mechanism on each shaft on corresponding sides of the standards, a shaft journaled on the base parallel to the concentric shafts, a plurality of actuating mechanisms journaled on said shaft, each adapted to actuate one of the registers, a lock for each register after the first pivoted to the appropriate standard and independent 100 transferring mechanisms between the parallel standards for transferring a count from the appropriate lower to the appropriate higher denomination register. 105 110

174. In a device of the class described concentric shafts, registering mechanism thereon appropriated to dollars, dimes and pennies, a total adding dollar register connected with one of the shafts and total adding wheels on the other two shafts to indicate the sum less than a dollar. 115 120

175. In a registering machine a totaling mechanism embracing a totaling register for dollars and numbered wheels for totaling the sum less than a dollar and the reading of the register and totaling wheels being in alinement, the odd number of register wheels rotatable in one direction and the even number of register wheels rotatable in the opposite direction. 125 130

176. In a registering machine a totaling mechanism embracing a totaling register for dollars, numbered wheels for totaling the sum less than a dollar and the reading 5 of the register and totaling wheels being in alinement, oppositely rotating registering mechanisms connected with the numbered wheels, a registering mechanism connected to operate the totaling dollar register and 10 rotating oppositely from the adjacent registering mechanism, a transferring mechanism for transferring a count from each lower denomination registering mechanism to the next higher and a locking device for 15 each registering mechanism after the first.

177. In a registering device concentric dollar, dime and penny shafts, dollar, dime and penny registering mechanism thereon, numbered dime and penny wheels secured 20 on the dime and penny shafts and a total adding dollar register connected to operate from the dollar shaft.

178. In a registering device concentric dollar, dime and penny shafts, dollar, dime and 25 penny registering mechanism thereon, numbered dime and penny wheels secured on the dime and penny shafts, a total adding dollar register connected to operate from the dollar shaft, means for throwing the total adding dollar register out of operation with the 30 dollar shaft, a transferring mechanism between each set of registering mechanisms, means for actuating each to transfer a count, and a spring for returning each transferring 35 ring mechanism to normal.

179. In a registering device concentric dollar, dime and penny shafts, dollar, dime and penny registering mechanism thereon, numbered dime and penny wheels secured on the 40 dime and penny shafts, a total adding dollar register connected to operate from the dollar shaft, means for throwing the total adding dollar register out of operation with the dollar shaft, independently rotatable 45 wheels for actuating each registering device, and a locking device for each registering mechanism after the first and released prior to each actuation of the registering mechanisms.

180. In a device of the class described registering mechanism appropriated to dollars, dimes and pennies, a sliding standard, a total adding dollar register secured thereto and 55 connected with the dollar registering mechanism, means for clamping the standard with the total adding register in operative position, and means for automatically adjusting the standard and total adding mechanism out of operative position when the 60 clamping means is released.

181. In a device of the class described registering mechanism appropriated to dollars, dimes and pennies, a sliding standard, a total adding dollar register secured thereto, 65 and connected with the dollar registering

mechanism, means for clamping the standard with the total adding register in operative position, means for automatically adjusting the standard and total adding mechanism out of operative position when the 70 clamping means is released, peripherally numbered registering wheels connected with the dime and penny registering mechanism to indicate sums less than a dollar, and mechanisms, one adapted to act singly or 75 both coöperate to transfer one count to the total adding dollar register when the sum indicated on the numbered registering wheels equals a dollar.

182. In a registering machine a plurality 80 of registering mechanisms appropriated to different money denominations, successive registering mechanisms adapted to operate oppositely from the preceding lower denomination registering mechanism, an actuating mechanism for each of the registering mechanisms adapted to directly register thereto, and transferring mechanisms for the registering mechanism and each transferring mechanism operating oppositely 85 from the preceding transferring mechanism.

183. In a registering machine registering mechanisms appropriated to different money denominations and direct actuating mechanisms and transferring mechanisms for the 90 registers so arranged that the actuating mechanisms actuate the registering mechanism on one stroke and the transferring mechanism actuates the registering mechanism on the reverse stroke of the actuating 95 mechanism, a centrifugal governor for controlling the rate of operation of the mechanisms of the machine, locking devices for the registering mechanisms, a total dollar adder and a total cents adder adjacent thereto, said 100 adders connected with the appropriate denomination registering mechanism.

184. In a device of the class described register wheels with peripheral teeth, journal pins secured to each register wheel, teeth pivoted on each journal pin, means preventing the teeth from yielding but in one direction, a spring holding each tooth normally extended, and said teeth on the alternate register wheels arranged to yield oppositely 110 thereby adapting the registers to operate oppositely.

185. In a device of the class described a dollar, a dime and a penny register, an actuating mechanism for each and a transferring mechanism comprising a rotatable shaft, an oscillating and rotatable shaft pivotally connected with said shaft, a cam lever rigidly secured thereto, a pawl rigidly secured to each end of the oscillatable and rotatable shaft, means rotatable with the dime register for actuating the lever and depressing the pawls, cams carried by the dime and the penny actuating mechanism, each adapted to engage the appropriate pawl at 120 125 130

the appropriate time to actuate the shafts, and means secured to one of the shafts for actuating the dollar register.

186. In a registering machine a transfer-
5 ring mechanism comprising a rotatable shaft, links secured thereto, a shaft journaled to said links, a pawl secured on each end of said shaft, a cam lever secured to the second named shaft, means for actuating the 10 cam lever to set the pawls, means for engaging one of the pawls for swinging the second named shaft and rotating the first named shaft, and an actuating member carried by the first named shaft.
187. In a device of the class described a dollar, a dime and a penny register, an actuating mechanism for each and a transferring mechanism comprising a rotatable shaft, an oscillating and rotatable shaft pivotally con-
20 nected with said shaft, a cam lever rigidly secured thereto, a pawl rigidly secured to each end of the oscillatable and rotatable shaft, means rotatable with the dime register for actuating the lever and depressing the pawls, a cam carried by the dime and the penny actuating mechanism each adapt-
25 ed to engage the appropriate pawl at the appropriate time to actuate the shafts, means secured to one of the shafts for actuating the dollar register, an adjustable standard, a total adder for dollars secured thereon and connected with the dollar register and means for automatically throwing the total adder out of operation to be set 30 back when released.

188. In a registering machine a trans-
ferring mechanism comprising a rotatable shaft, links secured thereto, a shaft journaled to said links, a pawl secured on each 40 end of said shaft, a cam lever secured to the second named shaft, means for actuating the cam lever to set the pawls, means for engag-
ing one of the pawls for swinging the second named shaft and rotating the first
45 named shaft, an actuating member carried by the first named shaft, a spring for actuating the transferring mechanism oppo-
sitely and a roller for engaging the cam lever forcing the mechanism to assume its
50 normal position.

189. In a device of the class described register wheels with peripheral teeth, journal pins secured to each register wheel, teeth pivoted on each journal pin, means prevent-
55 ing the teeth from yielding but in one direction and a spring holding each tooth normally extended.

190. In a device of the class described register mechanisms appropriated to dif-
60 ferent denominations, a transferring mech-
anism and a rotatable direct actuating mech-
anism for each register after the first, the
rotatable mechanism adapted to actuate the
registering mechanism on the down stroke
65 and the transferring mechanism adapted to

actuate the registering mechanism on the return stroke of the direct actuating mech-
anism or vice versa, an actuating mechanism
for the first register and a locking mech-
anism for each register after the first adapt-
70 ed to be released by the appropriate direct
actuating mechanism and by the transfer-
ring mechanism.

191. In a device of the class described register wheels with peripheral teeth, journal pins secured to each register wheel, teeth pivoted on each journal pin, means prevent-
75 ing the teeth from yielding but in one direction, a spring holding each tooth normally extended, said teeth on the alternate register wheels arranged to yield oppositely thereby adapting the registers to operate oppositely, locks for engaging the peripheral teeth and holding the registers except the first from registering movement, and actuating mechanisms for the registering wheels adapted to engage the pivotal teeth to actuate the register wheels and to release the lock before engaging the pivotal teeth.

192. In a registering machine a plurality of registering mechanisms appropriated to different money denominations, successive registering mechanisms adapted to operate oppositely from the preceding lower de-
90 nomination registering mechanism, an actuating mechanism for each of the registering mechanisms adapted to directly register thereto, transferring mechanism for the registering mechanism and each trans-
ferring mechanism operating oppositely from 100 the preceding transferring mechanism, and a locking mechanism for each registering mechanism after the first.

193. In a device of the class described registering mechanism appropriated to dol-
lars, dimes and pennies, a sliding standard, 105 a total adding dollar register secured thereto and connected with the dollar registering mechanism, means for clamping the standard with the total adding register in oper-
ative position, means for automatically adjust-
ing the standard and total adding mech-
anism out of operative position when the 110 clamping means is released, and peripher-
ally numbered registering wheels connected 115 with the dime and penny registering mech-
anism to indicate sums less than a dollar.

194. In a registering device concentric dollar, dime and penny shafts, dollar, dime and penny registering mechanisms thereon, numbered dime and penny wheels secured on the dime and penny shafts, a total adding dollar register connected to operate from the dollar shaft, means for throwing the total adding dollar register out of operation 120 with the dollar shaft, a transferring mech-
anism between each set of registering mech-
anisms, means for actuating each to transfer a count, a spring for returning each trans-
ferring mechanism to normal, and axially 130

- aligned mechanisms, one appropriated to each registering mechanism and adapted to register directly thereto and to actuate alternate registering mechanisms oppositely. 65
- 5 195. In a registering machine a totaling mechanism embracing a totaling register for dollars and numbered wheels for totaling the sum less than a dollar, the reading of the register and totaling wheels being in alignment, oppositely rotating registering mechanism connected with the numbered wheels and a registering mechanism connected to operate the totaling dollar register and rotating oppositely from the adjacent 70 registering mechanism. 10
196. In a registering device concentric dollar, dime and penny shafts, dollar, dime and penny registering mechanisms thereon, numbered dime and penny wheels secured 75 on the dime and penny shafts, a total adding dollar register connected to operate from the dollar shaft and means for throwing the total adding dollar register out of operation with the dollar shaft. 15
- 25 197. In a registering machine a totaling mechanism embracing a totaling register for dollars, numbered wheels for totaling the sum less than a dollar and the reading of the register and totaling wheels being in alignment, oppositely rotating registering mechanism connected with the numbered wheels; a registering mechanism connected to operate the totaling dollar register and rotating oppositely from the adjacent 90 registering mechanism, a transferring mechanism for transferring a count from each lower denomination registering mechanism to the next higher, a locking device for each registering mechanism after the first, and rotating mechanisms for directly actuating the registering mechanisms. 95
- 30 198. In a registering device concentric dollar, dime and penny shafts, dollar, dime and penny registering mechanism thereon, numbered dime and penny wheels secured 100 on the dime and penny shafts, a total adding dollar register connected to operate from the dollar shaft, means for throwing the total adding dollar register out of operation with the dollar shaft, and independently rotatable wheels for actuating each registering device. 105
- 35 199. In a device of the class described concentric shafts, registering mechanism thereon appropriated to dollars, dimes and pennies, a total adding dollar register connected with one of the shafts, total adding wheels on the other two shafts to indicate the sum less than a dollar, mechanisms rotating the adjacent register mechanisms oppositely in registering, and transfer mechanisms also operating the registering mechanisms oppositely. 110
- 40 200. In a device of the class described a registering device comprising a base, parallel standards rigidly secured thereto, concentric shafts journaled in the standards, a registering mechanism on each shaft on corresponding sides of the standards, a shaft journaled on the base parallel to the concentric shafts and a plurality of actuating mechanisms journaled on said shaft, each adapted to actuate one of the registers. 115
201. In a device of the class described a plurality of standards, concentric shafts journaled thereto, oppositely rotatable registers secured to the shafts, oppositely acting transferring mechanisms journaled between the standards and mechanism for actuating the transferring mechanisms to transfer a count to the proper registers, locking mechanisms for the dollar and the dime register pivoted to the standards, one of said locking mechanisms actuated by one of the transferring mechanisms and means 120 rotatable on one of the shafts for actuating the other transferring mechanisms. 125
202. In a device of the class described a registering device comprising a base, parallel standards rigidly secured thereto, concentric shafts journaled in the standards, a registering mechanism on each shaft on corresponding sides of the standards, a shaft journaled on the base parallel to the concentric shafts, a plurality of actuating mechanisms journaled on said shafts, each adapted to actuate one of the registers, a lock for each register after the first pivoted to the appropriate standard, independent transferring mechanisms between the parallel 130 standards for transferring a count from the appropriate lower to the appropriate higher denomination register, an adjustable dollar adding register and numbered register wheels adapted to total the sum less than a dollar. 135
203. In a device of the class described a dollar and a penny register rotatable in the same direction, a dime register rotatable oppositely therefrom and oppositely acting transferring mechanisms for actuating the dime and the dollar registers oppositely in transferring a count thereto. 140
204. In a device of the class described a dollar, and a penny register rotatable in the same direction, a dime register rotatable oppositely therefrom, oppositely acting transferring mechanisms for actuating the dime and the dollar registers oppositely in transferring a count thereto, a total adding register connected with the dollar register, oppositely rotatable wheels adjacent the total adding register for indicating the sums less than a dollar, mechanism for shifting the total adding dollar register out of operation, and means for turning the same to normal. 145
205. A registering mechanism comprising registering wheels appropriated to money 150

- denominations, the odd number of register wheels rotatable in one direction and the even number of register wheels rotatable oppositely therefrom, a shaft, and independent 5 actuating mechanisms for the oppositely acting registers, all of said mechanisms mounted on said shaft and rotatable independently of each other.
206. In a device of the class described dollar, dime and penny registers, actuating mechanism therefor, a transferring mechanism for dimes and for dollars, a mechanism for actuating the dollar transferring mechanism when the dime registers a dollar, another mechanism for actuating the dollar transferring mechanism when the combined sum of the dime and penny register amounts to a dollar, a total adding register registering dollars and computing wheels adjacent thereto for indicating the total amount less than a dollar.
207. In a device of the class described concentric shafts, a penny register on one shaft, a dime register on the other shaft rotatable oppositely from the penny register, independent mechanisms for actuating the penny and dime registers oppositely, a lock adapted to prevent rotation of the dime register, a plurality of members rotatable with the 25 penny shaft, a transferring mechanism operated by one of the members and the other member adapted to release the lock from the dime register.
208. In a device of the class described concentric shafts, a penny register on one shaft, a dime register on the other shaft, a transferring mechanism comprising a ratchet wheel on the dime shaft, a pawl for actuating the same, a vertical lever pivotally connected with the pawl, an arm on the penny shaft for engaging the lever thereby actuating the dime register, a lock for the dime register, means for retracting the lock and an arm rotatable with the penny shaft for actuating the retracting means.
209. A registering mechanism comprising registering wheels appropriated to money denominations, the odd number of register wheels rotatable in one direction, and the even number of register wheels rotatable oppositely therefrom, a lock for each after the first, a transfer mechanism between each pair of register wheels adapted to release the lock and actuate the higher denomination register wheel, direct registering mechanisms for the register wheels adapted to engage and release the lock for the respective register wheel before actuating the same, a total adding register connected with the highest denomination register, wheels connected with the lower denomination registers having numerals thereon to read in alignment with the total adding register, and means for disconnecting the total adding register from the highest denomination register wheel to permit the total register being set back to normal.
210. In a device of the class described a register wheel having peripheral teeth, a pivotally supported locking lever having the end on one side of the pivot pawl shaped to engage the teeth, a pin secured to the lever on the opposite side of the pivot, a transferring mechanism for actuating the register wheel, means operated by the transferring mechanism for engaging the pin and swinging the pawl end of the lever out of engagement with the registering mechanism, a detent pivoted to the lever between the pivot point and pin, and releasable in one direction and an actuating wheel for engaging the detent to release the pawl and for actuating the registering wheel when the pawl is released.
211. In a device of the class described the combination with a registering wheel having peripheral teeth and pivotal teeth, a lock for engaging the peripheral teeth, a rotatable mechanism for successively releasing the lock and engaging the pivotal teeth to actuate the registering wheel between successive oscillations, and a transferring mechanism adapted to oscillate the lock and advance the registering wheel when the rotatable mechanism is at rest or rotating reversely to normal.
212. In a total adding register, register wheels, a lock for each after the first, a transfer mechanism between each pair of register wheels adapted to release the lock and actuate the higher denomination register wheel, direct registering mechanisms for the register wheels adapted to engage and release the lock for the respective register wheel before actuating the same, a total adding register connected with the highest denomination register, wheels connected with the lower denomination registers having numerals thereon to read in alignment with the total adding register, and means for disconnecting the total adding register from the highest denomination register wheel to permit the total register being set back to normal.
213. In a device of the class described a toothed register wheel, a lever for engaging the successive teeth and locking the wheel from rotation, a transferring mechanism for actuating the register, means actuated by the transferring mechanism to release the locking lever from the register wheel, a spring for returning the locking lever to normal, a rotatable direct registering mechanism for actuating the register and a detent pivoted to the lever by means of which the rotatable direct registering mechanism releases the locking lever when rotating in one direction but does not release the locking lever on reverse rotation.
214. In a device of the class described a registering wheel, a lock therefor, a combined transferring and lock releasing mechanism adapted to first release the lock and then actuate the registering wheel, a direct actuating mechanism for registering to the register adapted to both release the lock and actuate the register wheel independently of the transferring mechanism, a total register connected with and counting one for each actuation of the registering wheel, and

mechanism for uncoupling the total register permitting said register being quickly set to zero.

215. In a device of the class described ¹⁵ concentric shafts, a total register on one of the shafts, a high denomination register wheel on the same shaft, register wheels on the other shafts of different denominations, mechanism for actuating each register ¹⁰ wheel to independently register and mechanism for transferring a count from one or

all of the lower denomination register wheels acting singly or conjointly to the total register.

In testimony whereof I have hereunto ¹⁵ subscribed my name in the presence of two subscribing witnesses.

CHARLES SULFER.
